DRAFTING OF TEXTILE FIBERS

Geoffrey Hill Ambler, Ben Rhydding, Ilkley, England, assignor to Ambler Superdraft Limited, Ilkley, England, a British company

Application March 22, 1950, Serial No. 151,136
In Great Britain April 11, 1947

38 Claims. (Cl. 19—130)

1

This invention relates to apparatus and methods for the drafting of textile fibres in the form of rovings or the like containing a small amount of twist, and more particularly it relates to such apparatus and methods adapted for what is known as "high drafting," i. e., drafting in a single stage to higher than the customary degree. The invention will be described with especial reference to the drafting of worsted fibres, but it may also be applied to the drafting of other fibres, such for example as cotton or staple fibres produced from synthetic filaments. This application is a continuation-in-part of my application Serial No. 18,524, filed April 2, 1948, now abandoned.

In the drafting of worsted, the range of draft is usually between 5 and 12, very commonly 6, with the result that after combing or gilling the slivers or slubbings need to be passed through many drafting machines in succession until they (in the form of rovings) reach a sufficient fineness for the final spinning operation. By the practice of the present invention, on the other hand, drafts even exceeding 200 for certain worsted counts may be achieved in a single stage, with the production of yarn of good commercial quality, and similarly very high drafts may be employed in working upon cotton and upon rayon staple fibre, with the reduction in each case of the number of drafting stages required and a very considerable reduction in the amount of machines required, with the attendant labour.

The invention will be described herein as applied to drafting in the final spinning operation, although it may equally be applied at earlier points in the preparation of fibrous material. For simplicity, the word "rovings" will be used herein to denote whatever assemblage of fibres is described as being drafted, such fibres being parallel, overlapping, and twisted together to form a continuous cylinder, and similarly the drafted product will be referred to as "yarn," although these terms are usually applied in the spinning industry only to drafting in the spinning frame and the drafted product thereof.

The object of the invention, generally speaking, comprises the provision of methods and means whereby a regular yarn will be produced at high drafts, with the minimum introduction of irregularities into the same during the drafting process, and whereby the apparatus may easily be set for the production of desired products, such as different counts of wool, at the optimum drafts therefor. The invention, so far as it relates to apparatus, includes the provision of means whereby existing drafting apparatus may

2

be modified to enable the process to be practised.

The invention is based upon certain discoveries relating to the forces which act upon and within a twisted roving during the drafting thereof, and to the conditions which must be satisfied in order that the fibres of the roving shall be presented smoothly and regularly to the drafting rolls, at various desired drafts.

10 In accordance with these discoveries, the invention is practiced by careful control and utilization of twist and tension in the roving, to maintain the fibres thereof in coherent condition at all points and to ensure regular feed to the drafting rolls. To this end, means are interposed between feed and drafting rolls, between which a twisted roving is progressing, which may be set at a distance from the drafting rolls determined to be appropriate for the desired draft and product (such as a particular wool count) to be obtained. This means, thus adjusted in position and also adjusted as to the pressure with which it bears upon the roving, will serve to control the twist distribution and tension in the roving both to the rear and forwardly from the same, in a manner which will produce the conditions which are necessary for smooth continuous drafting.

This means, in its preferred form, comprises forwardly-moving surfaces, preferably small rollers, adapted to urge the roving, passing between them, forwardly at a speed such as to ensure that the length of roving rearwardly therefrom will remain taut, and adapted to press upon the roving with sufficient force to apply required tension thereto. Also preferably these surfaces are so flanged or shaped as to compress the roving between them into a rectangular or other solid cross sectional form. Also, preferably, the means referred to includes a device in front of the small rollers, through which the roving passes, and which is so shaped as to prevent sensible rotation of a length of roving contained therein. Also, preferably, a similar device, having the same purpose, is provided behind the small rollers. All of these members may be carried by a common support which may be adjusted by suitable means towards or away from the nip of the drafting rolls. The invention, as apparatus, also comprises various combinations of parts and details of construction, and, as a sub-combination, the provision of a detachable unit comprising the common support referred to above with the devices carried thereby, including gearing or other power transmission means adapted to cooperate with a gear or

other appropriate member of the main apparatus, this being adapted to be added to an existing apparatus, in modifying the same for the practice of the present invention.

The process invention herein described involves the use of rovings of appropriate size and initial twist, the application of pressure of appropriate amount upon the roving at the point where it passes between the small rollers or the like referred to above, and the setting of these rollers (and of the first named rotation-preventing device if used) at proper distances from the drafting rolls, all as will be explained hereafter. As to this setting, the process step, speaking more broadly, consists in the setting, nearer to or further away from the nip of the drafting rolls, of the point in the roving nearest to the drafting rolls at which rotation of the roving is prevented.

The invention will be described in connection with the accompanying drawings, showing preferred embodiments of the apparatus, together with diagrams illustrating points required in the understanding of the process. In the drawings:

Figure 27 is a view similar to Figure 26, showing a portion of the unit;

Figure 28 is a front view of the "twist stabilizer" shown in Figures 22 and 24;

Figure 28A is a side view of the same;

Figure 29 is a plan view of a greater part of one embodiment of the drafting apparatus than is shown in Figure 22, viewed in the direction of the arrow A in Figure 22, and drawn to a smaller scale than Figure 22;

Figure 30 is a sectional elevation of part of the apparatus shown in Figure 29, but drawn to a somewhat larger scale;

Figure 31 is a diagram showing loading curves for the anti-rotation device L flume, which may be used;

Figure 32 is a diagram showing variations of cross sectional area of rovings at different drafts, at different distances from the drafting rollers;

Figure 33 is a similar diagram but showing variations in diameters of the rovings;

Figure 34 is a diagrammatic showing of a pair of drafting rollers, one having a soft resilient cover, so arranged that the tangents to the arcs of the rollers meeting at the nip points subtend an appreciable angle;

Figure 35 is a showing of curves indicating relation between angles of incidence of the peripheral arcs of the rollers, meeting at the nip points, and various depression values for the comparatively soft roller cover;

Figure 36 is a diagrammatic showing of a pair of drafting rollers, indicating the displacement effect of depression when the soft cover is not sufficiently radially resilient;

Figure 37 is a section through a pair of drafting rollers, showing diagrammatically a preferred construction of the hard roller; and

Figure 38 is a diagrammatic elevation of the drafting rollers in one embodiment of the invention, showing the pressure-applying mechanism.

Brief description of apparatus.—A general description of apparatus constituting one embodiment of the apparatus invention will first be given, this to be followed by a discussion of theoretical considerations and the process developed therefrom. Referring to Figure 1, a roving 1 is shown as passing through the nip of a pair of feed rollers 2, 3 and through a roving guide 4 to the nip of a pair of small intermediate rollers 5, 6 and from there through a channel-shaped member 7 to the nip of a pair of front or drafting rollers 8 from which it passes in the form of yarn 9 to the bobbin of a cap-spinning device of known construction and generally indicated by reference numeral 10.

The lower feed roller 3, in the embodiment illustrated, is formed with a pair of flanges 11 between which the upper feed roller 2 fits closely,

The roving fed therethrough is therefore somewhat compressed in its passage between the cylindrical surfaces and the side flanges, into a rectangular cross section.

The lower of the intermediate rollers 6 is shown as being formed with a pair of flanges 12 between which the upper roller 5 fits closely and rests on the roving 1 passing between the flanges. The lower roller 6 is rotatably mounted in suitable bearings in a common support 13 and is driven by a pair of small gears 14, 16 from a driving gear 17 mounted on a driving shaft 18 (see Figures 3 and 4), mounted in bearing members 19. The upper roller 5 preferably is fluted and is mounted in suitable bearings in a supporting bracket 21 pivoted at 22, on the common support 13, so as to be capable of swinging upwardly for threading purposes. Removable weights 23, of which a number of different weights may be supplied for alternative use, are carried on the bracket 21 for supplying necessary pressure upon the roving between the rollers 5 and 6. The roving is therefore compressed into a rectangular cross-section in its passage between these rollers 5, 6 by the cylindrical surfaces and the side flanges thereof.

The upper roller 5 is driven positively at the same peripheral speed as the lower roller 6 from a gear 24 mounted on a shaft 26 passing through the common support 13 and to the other end of which is secured the gear 14. The gear 24 drives an intermediate gear 27 freely mounted in the common support 13, the gear 27 driving a further gear 28 mounted on the shaft of the upper roller 5. The intermediate gear 27 is so positioned that the gear 28 rolls around it during pivotal movement of the bracket 21.

Rollers 5, 6 are of very small size, because of the limited space close to the drafting rollers when drafting to a high degree, for which reason it is desirable that both of them be positively driven, as stated above, since with such small rollers it would be inadvisable to rely on driving the upper roller 5 through the material itself from a driven bottom roller. For use with 4" diameter front rollers 8 (a usual size for worsted), the intermediate rollers 5, 6 may need to be as small as $\frac{1}{4}$ " diameter or, generally speaking, they should be less than $\frac{1}{10}$ the diameter of the drafting rollers. In drafting fibres of short staple such as cotton, on the other hand, the drafting rollers may be much smaller, say 1" diameter, and in such a case, the intermediate rollers would generally be less than $\frac{1}{4}$ the diameter of the drafting rollers.

These intermediate rollers are required, as one function, to engage the roving frictionally and to urge it forward while maintaining it under desirable tension. They are therefore driven at a peripheral speed slightly in excess of the peripheral speed of the feed rollers, preferably an excess of about 8 per cent. The pressure applied to the roving through the top roller 5 must be sufficient, *inter alia*, to hold the length of roving extending from the feed rollers to the intermediate rollers 5, 6 taut, but it must not be sufficiently great to cause the intermediate rollers to so grip the roving as to produce appreciable drafting action at or rearwardly from the nip of the intermediate rollers.

There will therefore be a certain slippage between these rollers and the roving, or stretching of the latter, or both. In the event that stretching takes place, it is preferable that the excess

speed of the intermediate rollers is sufficient to give a slight lead after allowing for the stretch. Obviously, the necessary pressure may be applied to the upper intermediate roller in various ways, the method of dead-weighting by removable weight, as illustrated, being a suitable method.

A weight of about 7.25 ozs. for the weight 23, shown in Figure 1, has been found suitable for various drafting operations upon wool qualities of standard type, the intermediate rollers being of the order of $\frac{1}{4}$ " diameter, although it should be understood that it may be necessary to adjust the weight to meet certain conditions, as will appear hereafter. The pressure due to this weight is increased by the weight of the pivoted bracket 21, which is slight, and by the downward force applied by the gear 27 through the gear 28 to the upper roller 5, when the machine is in operation. The area of contact between the top roller and roving is small, and the weight of 7.25 ozs. referred to corresponds, under the conditions indicated to a pressure of about 70 lbs. per sq. inch upon the roving.

The channel-shaped member 7, or "flume," as I will term it hereafter, designed to prevent substantial rotation of the length of roving moving forwardly therethrough, provides an elongated channel, preferably substantially rectangular in cross section and formed at the back end with a flared mouth 37 for threading purposes, as is indicated in Figure 5. It is preferably removably mounted up on the common support 13 and has its base extended between the flanges 12 of the roller 6, this serving to act as a scraper, and to position the flume 7, laterally, and to cause the channel through the flume to form with the opening between rollers 5, 6 a substantially continuous passageway. Its length may be of the order of 0.75 inch, and the width of its channel may vary suitably, from .075 inch at the rear end to .065 inch at the front end, when the width between the flanges 12 of the lower roller 6 is .075 inch.

Further description of this member will be given at a later point. For the present it is only necessary to say that it must be so designed, in relation to the initial size of twisted roving used, as to provide surfaces which engage the periphery and so distort the cross sectional shape of the roving as to prevent substantially all rotation thereof throughout its passage through the flume.

The common support 13, as shown in Figure 1, is supported on a bearing formed by the upper surface of the adjacent bearing member 19. As shown, it is secured to a traversing bracket 31 in a quickly detachable manner by a pair of pins 32 extending from a pair of spring clips 33. The bracket 31 is secured to a traversing shaft 34 slidably mounted in lugs 36 extending from the bearing members 19.

The unitary structure comprising the common support 13, roving guide 4, intermediate rollers 5, 6, together with the gearing described and the flume 7, constitutes the intermediate unit referred to, and by movement of the bearing members 19 in the manner explained later, the unit together with the driving shaft 18 and the traversing shaft 34 may be adjusted in position towards and away from the nip of the drafting rollers. To this may also be added another flume, extending rearwardly from rollers 5, 6 as will be described hereafter.

The mechanism generally described above constitutes a drafting unit of which one is provided for each spindle in a spinning frame. It is intended that the units should be arranged in sec-

tions of, say, eight units, each section being mounted by means of bearing members 19 on a common supporting bar 38, the various shaft sections 18 rotatably mounted in the bearing members 19, being connected by couplings 39 and driven from a common source. Traversing of the various units in the sections is effected by reciprocating the traversing shaft 34.

The various supporting bars 38 may be secured at each end to adjusting brackets 41 slidably mounted on tubular members 42 and means are provided for adjusting the brackets 41 simultaneously towards or away from the drafting rollers 8 for different draft conditions.

Further description of apparatus will be given at a later point. It seems desirable at this time to discuss the theoretical considerations on which the invention is based.

Theoretical considerations, in general.—In the present process a roving of substantial uniformity, and uniformly twisted, is passed through the feed rollers at a constant rate and progressed to the drafting rollers, where fibres presented thereto in turn are seized and passed forward continuously at a higher rate, being extracted or drawn forwardly over the other fibres which are yet to be presented to the drafting rollers. The peripheral speed of the drafting rollers is, of course, that of the feed rollers multiplied by the draft.

This roving is made up of fibres which may be and usually are of different lengths, which overlap each other in length. The distance between the feed and drafting rollers should be slightly greater than the length of the longest fibre in the roving, as otherwise there would be breakage of fibres gripped at the same time both by feed and drafting rollers. At any moment during drafting some of the fibres are gripped by the feed rollers and move at their (slow) speed, these being known as "back fibres." Some of the fibres, known as "front fibres" are gripped by the drafting rollers, and move at their (faster) speed, while some fibres, known as "free fibres" are gripped by neither feed nor drafting rollers.

Ideal drafting, which produces regular yarn, of constant cross section (provided that the initial roving is regular), requires that all fibres should be moved steadily forward from back to front (or drafting) rollers, and be presented in order to the latter. To accomplish this, what I term "fibre control" is required, with the aim, *inter alia*, of causing both the back and free fibres to move only at back, that is, feed roller speed. Irregularities in the yarn produced may be caused either by fibre breakage or by free fibres moving forwardly out of turn.

It is therefore a requirement for good drafting, in such a system as I am describing, that the free fibres be bound in some way to the back fibres sufficiently to cause them to move at the back fibre speed, and that the front fibres be able to pull the free fibres forward regularly, while at the same time the front fibres can be extracted by being pulled forwardly over the free fibres. In the process now described, the whole twisted roving, from back to front rollers, is maintained under longitudinal tension, this providing the force which pulls the fibres forwardly.

Expressed differently, it is therefore necessary that the whole length of roving, from back to front rollers, be sufficiently coherent, it being said to be "coherent" when considerable outside force is required to cause longitudinal movement

between fibre and fibre. This coherence is caused, in the present process, by a combination of twist and tension, both suitably controlled. This combination causes a resultant force which acts towards the centre line of the roving and binds the fibres together, the friction between the fibres resulting from this binding force causing resistance to longitudinal movement of one fibre along another. The degree of coherence in the front part of the roving must, however, not be so great as to prevent the extraction of the front fibres, or fibre breakage will result.

The manner in which both twist and tension operates, and are controlled, in the present process, must therefore be examined, and a start will be made with twist. It should be noted that the necessity of understanding and utilizing the forces referred to, in order to achieve good drafting, is very much greater in the case of high drafting than in the case of conventional low drafting.

Provision and utilization of twist.—The cross sectional area, or drams weight per forty yard length of roving, progressively decreases with approach to the drafting rollers. If an initially uniformly twisted roving is passed from the feed to the drafting rollers without the interposition of intermediate rollers, the initial twist distributes itself non-uniformly along the material, so that a greater rate of twist will be found as the cross-sectional area diminishes with closer approach to the front rollers.

To discover the twist distribution in a roving undergoing drafting, it is first necessary to consider the variation of different fibre lengths therein. In most fibrous materials, considerable variation in fibre length is found, and the preliminary treatment of the material is largely directed to distributing the variations uniformly throughout the length of the material, first in the top, and next in the sliver. Even in the case of staple fibre of uniform length cut from synthetic or artificial filaments breakage during early treatment produces considerable variation in fibre length. Analysis of a sample enables the variation to be classified as percentages of fibres lying within a number of ranges of length.

Such a fibre length analysis may be made in a machine which separates the fibres into bundles having different length ranges, this as a preliminary to the determination of the varying thickness of the roving being drafted at any draft. The variation in length of the fibres can thus be classified as percentages of fibres lying within a number of ranges of length. Similarly, separate analysis of two or more samples may be combined to give an analysis of a blend of two or more qualities.

Having obtained such analysis, the length ranges can be superposed on a base line corresponding to the longest fibre to form a fibre length diagram of the sample or blend. Figure 6 shows such a diagram obtained from a blend of 64's and 70's wool tops in the proportion of 3 to 1, the maximum fibre length being of the order of 6 inches.

A "draft pattern," for any given draft, can now be obtained, by subjecting all the fibres to that draft, each bundle of any one length range being subjected to drafting in turn, to obtain the diminution in cross-sectional area of each such bundle as it approaches the drafting rollers. Bearing in mind that no diminution of any bundle can commence until the forward ends of the fibres in that bundle reach the drafting

rollers it will be seen that the diminution in cross-sectional area of the whole of the material may be obtained by superposing the results obtained from the consideration of the several bundles. Accordingly a plot of the sum of the results obtained from the several bundles against the length of the longest fibre may be made, this producing a draft pattern. A draft pattern of the blend above referred to is shown in Figure 7, this being at a draft of 6.5, the curve showing the way in which the cross-sectional area of the combined bundles of material decreases, in the case illustrated, as the position of the drafting rollers is approached.

We are now in a position to ascertain the distribution of twist in such a roving. I have found that when a roving, sliver, or other twisted bundle of varying cross-sectional area is freely suspended between two points, the rate of twist at any cross-sectional area r is governed by the equation:

$$t = T \left(\frac{R}{r} \right)^x$$

Where T = average rate of twist throughout the bundle and R = the cross-sectional area of the bundle where the rate of twist = T .

By use of the varying cross-sectional areas r obtainable from the draft pattern, a factor of the above expression, namely

$$\frac{1}{r^x}$$

can be plotted against distance along the roving, giving a curve representing a function of twist. Though this does not give an absolute measure of rate of twist, it may be regarded as a "twist pattern." An approximate value for x for a typical sample of worsted fibre of 0.735 was found experimentally, and this figure has been used satisfactorily in subsequent drafting of worsted fibre.

A twist pattern obtained from the draft pattern shown in Figure 7, using a value for x of 0.735, is shown by the chain-dotted curve X in Figure 8, in which the nip points are indicated by feed and drafting rollers 2 and 8, respectively. Now the curve X represents the twist distribution in the draft zone, i. e., the distance between the nip points of the feed and drafting rollers 2 and 8, in a roving whose cross-sectional area varies according to the draft pattern shown in Figure 7, as it would appear if it could be freely suspended between the nips of the feed and drafting rollers and the initial twist in the roving allowed to distribute itself over that length before the commencement of the drafting action.

Considering the effect of drafting under the above conditions, once equilibrium has been established in the system, the twist rate in the portion of the roving presented to the drafting rollers will be equal to that in the portion of the roving presented to the feed rollers. This statement can be put in a more general form. As shown above, there is a progressive reduction of roving thickness from the feed rollers to the drafting rollers, and the twist will therefore "run" to the front of the draft zone. Any "run" of twist, i. e., increase in the rate of twist, is accompanied by a rotation of the roving. Anything which stops this rotation must stop the twist "run," and this is of course the effect of the gripping of the front fibres by the drafting rollers. The same effect takes place whenever the rotation of the roving is prevented at any point, as at its passage through intermediate rollers,

presently to be described, and at all such points the rate of twist is found to be the same as the initial twist rate of the roving just prior to its entrance between the feed rollers.

It will also be observed from Figure 8 and following figures that the rate of twist drops from its initial rate immediately it has passed through the feed rollers. Incidentally Figures 8-18 inclusive are not intended to show the correct relative sizes and positioning of the various rollers, these figures being merely mathematical diagrams.

Now referring again to Figure 8, because the twist rates at the nips of the feed and drafting rollers are equal during the drafting operation, a second curve Y can be produced from the curve X by taking the final vertical ordinate of the curve X as proportional to the initial twist indicated by the ordinate BC in the undrafted roving, and reducing the remaining ordinates proportionately. The curve Y , therefore, shows the twist distribution between the feed and drafting rollers during their drafting operation, the total twist in the portion of the roving undergoing drafting being represented by the shaded area below the curve Y in Figure 8.

The twist conditions indicated by the curve Y in Figure 8 assume that drafting takes place between the feed and the drafting rollers without the interposition of intermediate rollers, so that the roving between the nip points is free to rotate about its own axis and allow the twist to distribute itself according to the above law in the manner indicated. A single twist system is thus set up in the roving between the nips of the feed and drafting rollers.

To summarize the explanation given in the preceding paragraphs: In the conditions of equilibrium achieved during drafting and shown by curve Y , there is an abrupt drop in the rate of twist to a low level immediately the roving passes the feed rollers; and the rate remains at this low level until near approach to the drafting rollers, when the twist distribution brings up the twist rapidly to the initial rate, i. e., the rate immediately approaching the feed rollers. Drafting can, in practice, be carried out to some extent under the twist conditions indicated by this curve Y , i. e., at a draft of 6.5, but the drop in the rate of twist in the roving as it passes through the feed rollers becomes increasingly severe with increasing draft. This is illustrated by Figure 9, which is a twist diagram that would obtain for the 64's/70's sample mentioned above, if it could be subjected to a draft of 120 in these circumstances. It will be seen that the twist falls to negligible proportions in front of the feed rollers, which would be inadequate to maintain coherence in the roving, so that drafting could not proceed.

I will now discuss the modifications in the twist distribution when a pair of small carrier or intermediate rollers is interposed, near to the nip of the drafting rollers, as is illustrated in Figures 10A, 10B, 10C, which also show the effect on twist distribution of positioning the intermediate rollers at different distances from the drafting rollers.

It will be seen that the effect of using the intermediate rollers, indicated at 5, is to divide the single twist system described above into two systems, (a) a front twist system extending from the nip of the drafting rollers 8, to the nip of the intermediate rollers 5, and (b) a rear twist system extending from the nip of the intermediate

11

rollers 5 to the nip of the feed rollers 2. Figures 10A, 10B, 10C show three different twist diagrams all for the 64's/70's quality used above when subjected to a draft of 6.5, the intermediate rollers in the three diagrams being positioned at different distances from the nip of the drafting rollers. The twist diagrams in the three cases are again proportional to the curve X in Figure 8, and it will be seen that the rate of twist in each case decreases progressively in the front twist system from the nip of the drafting rollers 8 towards the nip of the intermediate rollers 5 where the twist is the same value as that at the nip of the drafting rollers, i. e., equal to the initial twist in the undrafted roving, and again in the rear twist system from the nip of the intermediate rollers 5 to the nip of the feed rollers 2.

Table A shows the relative twist values for three different positions of intermediate rollers corresponding to those illustrated in Figures 10A, 10B and 10C, respectively.

TABLE A

[Draft = 6.5. Initial roving twist rate = T turns per inch]

Distance between intermediate roller nip and drafting roller nip	Average twist rate in rear twist system (turns per inch)	Average twist rate in front twist system (turns per inch)
1 inch.....	.867T	.434T
2 inches.....	.98T	.35T
3 inches.....	.996T	.318T

It will be seen, therefore, that by movement of the intermediate rollers towards the nip of the drafting rollers the average rate of twist in the rear twist system is progressively decreased while that in the front twist system is progressively increased.

Figures 11A, 11B and 11C show a set of diagrams similar to those in Figures 10A, 10B and 10C except that the position of the intermediate rollers 5 is the same in the three cases. The draft, however, is increased from 20 in Figure 11A to 80 in Figure 11B and to 120 in Figure 11C. The effect of this is progressively to reduce the average twist rate in both the front and rear twist systems and it will be seen that such reduction is of far greater magnitude in the front twist system than in the rear twist system in each case. Table B shows the relative twist values corresponding to the three twist diagrams illustrated in Figures 11A, 11B, and 11C.

TABLE B

[Intermediate roller nip at 2" from drafting roller nip. Initial roving twist rate = T turns per inch]

Draft	Average twist rate in rear twist system (turns per inch)	Average twist rate in front twist system (turns per inch)
20.....	.944T	.203T
80.....	.94T	.0827T
120.....	.939T	.068T

It will be seen from a comparison of Tables A and B and the above described figures that increasing the draft decreases the average twist rate in the front twist system very considerably, if the intermediate rollers are left in the same position, while moving the intermediate rollers towards the draft rollers, the draft remaining the same, increases the average twist rate in the front zone, although to a less extent than the opposite effect caused by increase of draft.

12

It is clear that the higher the draft the more necessary it becomes to provide an adequate rate of twist in the front twist zone, and it is evident that moving the intermediate rollers forward, with increase of draft, will compensate to some extent for the reduction in the twist rate in the front zone caused by the increased draft. This compensation will be enough to enable commercial drafting to be practised at drafts somewhat above normal, but, if nothing more is done than is above indicated, the average twist rate in the front zone would become so low at considerably increased drafts, even with the intermediate units in a forward position, as to make the drafting operation commercially impracticable.

The increase in the front zone average rate of twist, which may be required for operating at high drafts, may be provided for by preventing rotation of a length of the roving forwardly from the intermediate rollers. This will now be described in connection with Figures 12A, 12B and 12C, these diagrams being for the same 64's/70's quality of roving as was dealt with above, and illustrating the twist distribution when drafting at 20, 80, and 120, respectively. These diagrams represent actual drafting conditions in the practice of my invention.

In these diagrams, the roving is urged forward, at a point between the feed and drafting rollers 2, 8, by a pair of small positively driven intermediate rollers 5 which may be of a flanged construction such as described in connection with intermediate rollers 5, 6 in Figure 1, and mounted as there described, with the upper roller exerting downward pressure upon the roving. Forwardly of these rollers, rotation of the roving about its own axis is prevented over a length extending towards the nip of the drafting rollers by the channel-shaped member 7 previously referred to as a "flume." These rollers and flumes will be more fully described later.

It will be seen from these diagrams that two twist systems again occur, but that the front twist system is now separated from the rear twist system by a twist zone corresponding to the area below the flume 7. Since the roving is prevented from rotating over its length which is passing through the flume, the twist over that length is prevented from running towards the nip of the drafting rollers, as explained above. The rate of twist thus remains constant throughout the length of the flume, despite the decrease in cross-sectional area of the roving as it passes forwardly through the flume, this rate of twist being equal to the initial twist in the roving.

The effect of preventing rotation of a front portion of the roving in this manner is to increase the average rate of twist (as compared with the use of intermediate rollers only) between the nip of the intermediate rollers 5 and the drafting rollers 8, as will clearly be seen from Figures 12A, 12B and 12C. In these figures, the intermediate rollers and flume have progressively been moved forward, nearer to the nip of the drafting rollers, as the draft has been increased. Table C shows the relative twist values and the setting of the intermediate rollers 5 and the flume 7 for the three twists diagrams in these figures, the flume 7 extending forwardly from substantially the nip of the intermediate rollers, and being .75 of an inch in length.

TABLE C

[Initial roving twist rate = T turns per inch]

Draft	Distance between intermediate roller nip and front roller nip	Average twist rate in rear twist system (turns per inch)	Average twist rate in front twist system (turns per inch)	Average twist rate between intermediate roller nip and drafting roller nip (turns per inch)
<i>Inches</i>				
120.....	1.17	.826T	.161T	.698T
80.....	1.3	.849T	.169T	.66T
20.....	2.07	.948T	.228T	.508T

In the drafting shown by this table, the initial twist rate would be something from .5 to 1 turn per inch, which was found generally to be satisfactory when drafting material such as a 36.6 dram worsted roving under the conditions noted. It will be seen that the average twist rates in the front twist system, between the front or exit end of the flume and the nip of the drafting rollers, are much higher for drafts of 80 and 120 than the twist rates for these drafts shown in Table B, and such values are found to be suitable for commercial drafting, at the drafts and setting distances for the intermediate rollers noted, suitable pressure upon the roving being provided by the weights 23 on brackets 21 referred to in connection with Figure 1.

Front rollers.—In drafting apparatus commonly used for drafting worsted fibres, the upper of the drafting rollers is covered with cork which yields somewhat under the pressure applied at the nip. The result of this is that the actual nip point is somewhat in advance of a line passing through the centres of the drafting rollers. It will therefore be understood that the expression "nip of the drafting rollers" used herein means the point on the meeting surfaces of those rollers at which the fibres are first nipped. There are special considerations in respect to the design of drafting rollers by which improved results when operating at high drafts may be obtained, as will be set forth at a later point.

Intermediate rollers, or equivalent.—There are also special considerations in respect to the intermediate rollers, or, more broadly speaking, the forwardly movable means which may be set at different distances from the drafting rollers to urge the roving forward. So far as the theory so far explained is concerned, the functions of urging the roving forwardly and applying pressure thereto can be performed by cylindrical unflanged rollers or equivalent means. If, however, unflanged rollers or small aprons or the like are used, the pressure applied to the top roller or equivalent will tend to flatten the roving at the nip into the form of a ribbon with the result that the twist in the roving is prevented from passing through the nip of the rollers, and is thus caused to "build up" between the intermediate rollers and the feed rollers, the effect of such "build up" being to cause an intermittent flow of twist. This can be prevented in either of two ways. Unflanged cylindrical intermediate rollers can be used, and a channel-shaped member, similar to the flume 7, previously described, mounted immediately behind the nip of the intermediate rollers so as to prevent rotation of the roving at that point, and thus force the twist in the roving through the nip of these rollers.

Or, and this is the preferable construction,

means may be provided in connection with the intermediate rollers for causing the roving passing through the same to be compressed into a solid cross-sectional form, as opposed to a ribbon-like form, in its passage therethrough. This can suitably be caused by providing one or both of the rollers with side surfaces: For instance, the lower roller 6 may be provided with two flanges 12, 12 as previously described in connection with Figures 1 and 4. The result of this construction is to squeeze the roving between the upper and lower cylindrical surfaces and the side flanges into a shape having a rectangular cross-section which may be approximately square, and with this construction the twist will pass continuously between the rollers. Preferably, also, similar means are provided at the feed rollers 2, 3 to cause the twist to pass therethrough, as by the provision of the flanges 11 on the lower feed roller 3 causing the roving to be compressed into a rectangular cross-sectional shape in its passage between these rollers.

The construction of the intermediate rollers with flanges, or other provisions for causing the roving passing therethrough to take a rectangular or other solid cross-sectional form, is advantageous also for another reason, in connection with the pressure applied to the roving through the top roller, which will be referred to more fully at a later point herein. Since there is little adhesion between the fibres, the roving as a whole is very flexible in cross-section. The total pressure existing between those two rollers and the roving is applied, therefore, almost equally to each fibre, in a manner similar to the three-dimensional transmission of pressure through a fluid contained in an enclosed vessel, such an arrangement being much more effective for the transmission of pressure to the roving (with consequent provision of tension therein), than a roller arrangement in which the roving is flattened to ribbon shape.

Whether or not a channel-shaped member is positioned rearwardly from the intermediate rollers, to prevent rotation of the roving at this point, for the prevention of building up of twist to the rear of these rollers, as previously mentioned, such a rotation-preventing member, either the same or another, may be desirable at a position between the intermediate and feed rollers for another reason. This is, to increase the average twist rate in the back twist zone, between the intermediate and feed rollers, which may sometimes be desirable if the initial twist in a given roving is found to be too low in front of the feed rollers to maintain adequate coherence in that region, although otherwise satisfactory for drafting purposes. This subject also will be referred to more fully presently.

Examples of usefulness.—With the apparatus and by the method so far described the coherence of the roving has been preserved under drafting conditions covering a very wide range of draft, and yarns of good commercial quality spun with very high drafts, e. g. drafts of up to 200 or more. Moreover, yarns can be spun at different drafts over a wide range from the same roving. For example, yarns of 10's, 30's, 48's and 60's worsted counts can be spun from a 36.6 dram roving, of 64's quality, with drafts of 20, 60, 96, and 120, respectively.

Examples of the use of the invention in the production of yarns of good commercial quality

are as follows:

15
EXAMPLE 1

[Quality—64's/70's wool. (Normal commercial draft 6.5)]

Draft	Roving	Yarn	Distance between the nips of intermediate and drafting rollers
20	36.6 drams per 40 yards.	10's worsted counts...	Inches 3.27
40	do	20's worsted counts...	2.18
60	do	30's worsted counts...	1.72
80	do	40's worsted counts...	1.45
100	do	50's worsted counts...	1.3
120	do	60's worsted counts...	1.25

In this example the channel-shaped member 7 was approximately .75 of an inch in length.

EXAMPLE 2

[Quality—80's wool. (Normal commercial draft 6.75)]

Draft	Roving	Yarn	Distance between the nips of intermediate and drafting rollers
204	45 drams per 40 yards.	80's worsted counts...	Inches 1.125

In this example the channel-shaped member 7 was approximately .75 of an inch in length.

EXAMPLE 3

[Quality—rayon staple fibre. 3 denier—maximum fibre length 4 inches. (Normal commercial draft 20)]

Draft	Roving	Yarn	Distance between the nips of intermediate and drafting rollers
70	73.2 drams per 40 yards.	16's worsted counts...	Inches 1.62
154	do	36's worsted counts...	1.28
260	do	60's worsted counts...	1.15

In this example the channel-shaped member 7 was approximately .6 of an inch in length.

In all the examples given above, the intermediate rollers 5 and 6 were .3 of an inch in diameter and were positioned immediately behind the channel-shaped member 7, the rollers being driven at a peripheral speed approximately 10% faster than that of the feed rollers 2 and 3. The width between the flanges 12 of the lower roller 6 was .075 of an inch. The width of the channel of the channel-shaped member 7 varied from .075 of an inch at the rear end to .065 at the front end.

Because of the close proximity of the mouth of the channel-shaped member 7 to the intermediate rollers 5 and 6 the flanges 12 of the lower roller 6 form, in effect, an extension of the sides of the channel of the channel-shaped member, with the result that the length over which rotation of the roving is prevented extends from substantially the nip of the rollers 5 and 6 to the front end of the channel-shaped member 7.

In addition to the above examples of commercial quality and production, yarns of a reasonably level nature have been produced experimentally on the above apparatus, according to the following examples.

16
EXAMPLE 4

[Quality—rayon staple fibre. 1½ denier—maximum fibre length 8 inches]

5	Draft	Roving	Yarn	Distance between the nips of intermediate and drafting rollers
10	1,000	104 drams per 40 yards.	175's worsted counts...	Inches 1.125

EXAMPLE 5

[Quality—Peruvian cotton. Maximum fibre length 1¾ inches]

20	Draft	Roving	Yarn	Distance between the nips of intermediate and drafting rollers
25	110	.4 bank	40's cotton counts...	Inches 1.15

Fibre control.—I will now proceed to explain more fully the theory of fibre control on which the invention is based, involving chiefly the function and control of tension as well as twist, with the aim of arriving at methods by which the apparatus can be adjusted quite accurately and operated under various conditions to obtain optimum results. These explanations will show methods of operating the apparatus without, as well as with, the use of the flume for preventing rotation of the roving in front of the intermediate rollers, drafting at a high rate being obtained without the flume when desired, although not so high as is obtainable when the flume is used.

Further discussion of twist controls.—I will start with a further draft diagram and a further brief consideration of twist control. Figure 13 is a draft zone diagram of a roving of 36.6 drams per 40 yards consisting of 64's/70 quality of wool, being subjected to a draft of 40. The yarn produced in this case would be 20's worsted counts. The cross-sectional area of the roving, decreasing progressively with approach to the drafting rollers, can, of course, readily be calculated by principles explained above. These values are plotted against ordinates of length measured back from the drafting roller nip point up to a distance equal to the length of the longest fibre. This gives the top curve R of the diagram, showing the thickness of the roving measured in drams per 40 yards, from the feed rollers 2 to the drafting rollers 8: this, of course, comprises all classes of fibres, back, free, and front.

The thickness of the front fibres only can be separately calculated and plotted against the same length ordinates. This has been done in this diagram, the lower curve F showing the thickness of the front fibres only. These are the fibres being continuously extracted, and for this reason the area lying between curve F and the base line may be termed thus "extraction area." The drafting and feed rollers are shown diagrammatically in their correct positions horizontally; also, the intermediate rollers 5 and the flume 7 are shown in position suitable to this particular draft and wool quality. The intermediate rollers 5 have an important function in applying tension to the roving, and will, accordingly be referred to hereafter, and indicated in the diagrams, as

"tension rollers." Also, the lengths of roving lying between the four contact points shown in the diagram will hereafter be referred to as follows: between feed rollers and tension rollers: back zone; between tension roller and flume exit; flume zone; and between flume exit and drafting rollers: front zone.

Figure 14 shows the twist rate distribution which relates to the draft zone diagram shown in Figure 13, the draft being 40 and the initial roving twist 0.6 turn per inch. Referring to Figure 13, it is seen that in each zone there is a progressive reduction of roving thickness from back to front. The twist will therefore "run" to the front of the back and front zones and be stopped by the prevention of rotation at the tension and drafting rollers, respectively. In the flume zone the rotation of the roving is prevented throughout the whole length of the zone, firstly by the tension rollers and secondly by the sides of the flume channel.

Referring to Figure 14 we see that the twist rate in the back zone, shown by curve TB, at points along the roving will relate inversely to the thickness of the roving at these points, rising, however, at the tension roller nip point to the same rate as that immediately behind the feed rollers, namely, 0.6 turn per inch, because of the fact that the roving rotation is stopped by the tension rollers. The mean twist rate for the whole length of roving in the back zone is, as shown, 0.561 per inch.

When the flume is placed immediately in front of the tension rollers, as shown, there is no sensible roving rotation in the flume zone, so that the initial roving twist rate, of 0.6 turn per inch, is maintained along the whole length of this zone, as shown at TFL, despite the fact that the roving weight per 40 yards is diminishing the nearer it gets to the flume exit.

The twist rate in the front zone is shown at TFR. It rises immediately behind the drafting rollers to 0.6 turn per inch, the same as the initial twist, from its lowest point immediately in front of the flume exit. At all intermediate points it is related inversely to the thickness of the roving in drams per 40 yards of the roving at these points. The mean twist rate for the whole zone is 0.1 turn per inch.

It should be observed that absolute twist rate is one thing and the effect of twist rate in contributing to roving coherence is another. In particular, this effect is in inverse relation to roving thickness: i. e. the thinner the roving, the less effective is a given rate of twist, and vice versa. Further, the effectiveness of twist depends upon the condition of the roving: this latter dependence will be discussed below. The total contribution made by twist to the coherence at any point will be referred to hereafter as "effective twist rate."

Figure 15 shows the effect of moving the tension rollers and flume one half inch forward. The tension rollers now make contact with a thinner part of the roving than was the case in Figure 14. The contacted point in the roving therefore takes up the same twist rate, 0.6 turn per inch, as the initial roving, all other points in the back zone taking up lower twist rates than 0.6 turn per inch in inverse relation to roving thickness. The mean twist rate in the back zone is now 0.533 turn per inch and therefore less than the Figure 14 value of 0.561. It will be seen by comparison of the two diagrams that the twist

rate curve in Figure 15 is lower than that in Figure 14 over the whole length of the back zone. Also, there has been no change of roving thickness in the back zone, and, therefore, forward movement of the tension rollers and flume has reduced both the mean twist rate and the effective twist rate over the whole length of this zone. Backward movement of the tension rollers and flume would have the reverse effect and result in a higher effective twist rate in the back zone.

Such forward movement of the tension rollers and flume, which may be required under various conditions, may lead to serious trouble in the back zone. For example, insufficient twist in the back zone, caused by such forward movement, may cause the roving coherence in that zone to be so much reduced that the roving cannot withstand the tension applied to it, and so breaks apart or greatly weakens at some point in that zone, causing unevenness of the yarn. Such a condition can of course be remedied by an increase in initial roving twist, but this would cause an increase also in the effective twist rate in both the other zones, which might not be required or desirable. Or the condition could be remedied by decreasing the tension, but difficulties may be met in adjusting the tension so that enough is provided where needed, as in the front zone, while at the same time it is not too much in the back zone, when the twist rate there is low. These difficulties can however be overcome by another means, which will increase the mean twist rate in the back zone while leaving the initial twist rate of the roving, and the tension, which is found suitable in other connections, undisturbed.

This means, or expedient, consists in fitting a channel-shaped member 7A like the flume 7 to enclose the roving in its channel for a distance of, say, 1½ inches behind the tension rollers. The anti-rotation properties of this device will maintain the initial roving twist rate (0.6 turn per inch, in the example given) throughout its own length. Also, since roving rotation in the back zone is now stopped at the back end of this device (where roving thickness is greater than at the tension rollers), the mean twist rate rearwardly from it is increased. Thus, this device increases both the mean twist rate and the effective twist rate in the back zone without affecting the other two zones. I will hereafter, for a short name, refer to this device as a "twist stabilizer."

The effect of the twist stabilizer, is shown in Figure 16, which is the same as Figure 15 except for the provision and effect of this member, which is indicated in the drawing at 7A. It will be seen that it is so positioned that its back end lies at a position which is on the comparatively flat part of the roving thickness curve R in Figure 13, where there is little variation in roving thickness. Thus, backward and forward movement of a unitary member carrying the tension rollers 5 and flume 7 as previously described, but additionally fitted with the twist stabilizer 7A, will make little difference in the mean twist rate or the effective twist rate in the back zone. Figure 16 shows the mean twist rate over the back zone to be 0.595 turn per inch, a substantial increase over the Figure 15 value of 0.533, and but little less than the initial roving twist rate of 0.6.

In connection with the above, it should be remarked that it is not essential that the "twist stabilizer" 7A be mounted on the common support 13 to form one of the devices carried by the unitary construction, adjustable in position as a

whole, as is indicated in the last paragraph. Such mounting is convenient, but it is only essential that it should be positioned somewhere between the tension and feed rollers, according to the twist conditions required.

Continuing consideration of the effect of moving the "unit," that is, the tension rollers and flume, forward, it will be seen that the flume zone in Figures 15 and 16 has the same twist rate as in Figure 14, 0.6 turn per inch, but the effective twist rate will be slightly reduced because the mean thickness of the roving has been reduced as a result of the forward movement down the taper of the roving. Backward movement of the unit would increase the effective twist rate in the flume zone.

In the front zone, the mean twist rate in Figure 14 is shown as 0.1 per inch and in Figure 16 as 0.135 turn per inch, so that the forward movement of the unit has increased the mean twist rate in the front zone. The minimum twist rate in both cases is at the point immediately in front of the flume exit. The twist rate curve in the front zone TFR is the same in both cases except that the Figure 15 or Figure 16 curve is shorter than in the case of Figure 14, because of the forward movement of the flume exit. Therefore, the minimum twist rate is greater in Figures 15 and 16 than in Figure 14, i. e., 0.057 in Figures 15 and 16 and 0.05 in Figure 14, this being an increase of 14 per cent. The mean roving thickness in the front zone and the thickness at the flume exit are both less in Figure 16 than in Figure 14.

For a number of reasons, the increase in twist rate is proportionately greater than the decrease in roving thickness, so that the effective twist rate in the Figure 16 case is slightly greater than in the Figure 14 case. Therefore, when draft is constant, forward movement of the "unit" slightly increases the effective twist rate in the front zone, while backward movement causes a slight reduction.

The forward movement of the flume has had another important effect in that the half inch length of the roving immediately in front of the flume exit in Figure 14 has been enclosed in the flume channel in Figures 15 and 16. This has resulted in a very large increase both in absolute twist rate and effective twist rate in that half inch length. Therefore the forward movement of the unit has created a length of relatively high effective twist rate condition further down the roving, and so enclosed more free fibres. Backward movement has the opposite effect.

There are only four ways of increasing the mean twist rate and effective twist rate in the front zone, namely:

(a) By reducing draft, i. e., making a thicker yarn from the same roving or the same yarn from a thinner roving; either way has the same result since they both reduce the difference between the two

$$\left(\frac{1}{r}\right)^{.73}$$

values (discussed in connection with Figure 7) at each end of the front zone.

(b) By moving the "unit" forward.

(c) By increasing the initial roving twist.

(d) By altering the shape of the draft zone diagram curve in the front zone, i. e., using a quality of material with a different fibre analysis.

Provision and control of tension.—The part played by tension in the process must now be

examined. I have indicated earlier herein the importance of tension in the process, acting as it does, together with twist, to set up a resultant force which acts towards the core of the roving, and, by causing inter-fibre pressure, tends to bind the fibres together. The provision of the necessary coherence requires adequate tension at any point where twist is low, particularly in front of the flume. At the same time, tension in the front zone must not be great enough to cause fibre breakage there, nor must tension in the back zone be great enough to cause parting of the roving in front of the feed rollers, if twist is inadequate in this area. This latter consideration does not arise in practice, if a twist stabilizer is mounted in the back zone. And as a further consideration, tension in the back zone must be adequate to hold the roving taut, since with any slackness there, the roving may be pulled through the tension rollers in a jerky and uneven manner. We must therefore consider the provision, control, and utilization of tension in all of the zones, back flume, and front.

The tension in the front zone is of course equal to the total pull exerted by the drafting rollers, which must be the same as the total resistance to extraction offered by the front fibres. This resistance is in my process predominantly due to the friction caused by dragging the front fibres through the portion of the roving which lies in the nip of the tension rollers, and may consequently be considered as compounded of three factors: (a) a constant related to the co-efficient of friction between fibres; (b) the loading of the top tension roller; and (c) the number of front fibres passing through the tension roller nip point.

Reference is made to Figure 17, which is merely an enlargement of the "extraction area" shown in Figure 13. The curve extending through points B and F to H is therefore equivalent to the curve F in Figure 13, showing the thickness of the front fibres only. It will be seen from this figure that forward movement of the tension rollers will increase the resistance to extraction by increasing factor (c).

Tension in the back zone is provided primarily by the forward slip of the tension rollers over the roving passing between them. The dead weight applied to the top tension roller can be varied by changing the weights fitted to the bracket which carries this roller. The tension applied to the roving is directly proportional to the dead weight thus applied. This tension is augmented (but when the draft is high, only slightly so), by the tension transmitted to the back zone from the front and flume zones resulting from the pull of the drafting rollers. It will be appreciated that tension in the front zone is transmitted to the flume zone, and, since the tension rollers have a speed lead over the speed of the roving passing between them, also to the back zone.

Initial twist rate.—Discussion of the provision of tension will be interrupted briefly for a discussion of the initial roving twist rate. It is of course obvious that for various thicknesses of roving and for drafting under various conditions the provision of suitable initial twist is important. Formulae exist for calculating the twist rate for a given thickness of roving, in which a constant is always used, to provide an effective twist rate to meet a required degree of coherence. Each textile material has its own constant, relating to such factors as co-efficient of friction

as between fibres, mean fibre diameter, and length, and fibre rigidity.

These constants, for natural textile materials such as wool, are however, unreliable, because of certain incalculable variants relating to degree of maturity, oil content, humidity conditions, and fibre brittleness. The best way of fixing initial roving twist rate therefore appears to be to make use of human skill, experience and "feel"; by allowing a qualified man to find, by trial and error, a twist rate which gives a suitable degree of coherence when the twisted roving is pulled apart manually. By this means a skilled man can "feel" the resistance to extraction and so estimate closely the degree of coherence.

The characteristics of a roving change in storage and with changes in atmospheric conditions, etc. It will be appreciated that when a roving is prepared such factors should be allowed for: the object being to produce a roving which will display proper coherence when it is subjected to drafting. Some margin must be allowed for unforeseen variations. Subject to this however it is preferable to aim at the use of rovings which will just withstand slight tension without disintegration. The employment of substantially more twist than is needed to produce this is deleterious. At extreme drafts (so high that it is impossible to bring the tension rollers as close to the nip of the drafting rollers as the instructions given hereafter for the attainment of optimum drafting conditions would require) it may however be necessary to employ more twist than this. Unforeseen variations in the condition of the roving can normally be compensated for by varying the weighting of the tension rollers as hereinafter explained.

Further discussion of tension and coherence.—The effective twist rate in the back zone is of a high order, at least if a twist stabilizer, as described above, is used. Tension is applied mechanically by the tension rollers and is reliably maintained. Therefore, if a suitable initial twist is used, a proper degree of roving coherence is assured, so that the roving will not part, nor will the degree of coherence cause fibre breakage. The degree of roving coherence in the back zone need not, therefore, concern us further.

Tension, in the back zone, is applied to the roving as an entity by the tension rollers, and is therefore carried by all the back and free fibres. They are themselves subjected to a high effective twist rate, so that roving coherence is achieved easily. In the front and flume zones, however, the main tension exists only in those front fibres which extend from the tension rollers (whence they gain the tension) through the flume and front zones. The free and back fibres in the flume and front zones are not under any substantial tension. The problem therefore is to bind these back and free fibres into a sufficient degree of coherence by the few fibres which are under tension.

The degree of resistance offered by the free and back untensioned fibres to this binding force will depend on their natural tendency to burst or spring apart, and this depends partly on the "crimp" in the fibre, and is related to the thickness of the fibre. The finest yarn count (limit count) to which a textile material can be spun has been found to be a good indication of fibre thickness. The higher the limit count, the finer will be the fibre, and in consequence the tendency to "burst" and resist the binding force will

be less. The value of the binding force will also depend on effective twist rate and the proportion of tensioned fibres.

A small proportion of tensioned fibres randomly arranged in the cross-section will cause an appreciable resultant force acting towards the core of the roving if the effective twist rate is high, while a larger proportion of tensioned fibres will be required if the effective twist rate is low.

Therefore, in the front and flume zones the degree of coherence will depend on:

(a) The fineness of fibre as indicated by limit count.

(b) The degree of tension in each of the tensioned fibres.

(c) The proportion of tensioned fibres in the roving cross-section, and

(d) Effective twist rate.

In the flume zone the effective twist rate is relatively high, so that notwithstanding the low proportion of tensioned fibres compared with back and free fibres, a medium degree of coherence will be provided in the latter. The effective twist rate in the flume zone is decreased

with forward movement of the adjustable "unit," but we see from Figures 13 and 17 that, as the flume zone is moved forward with the "unit," (1st), the number (cross-sectional area) of the tensioned fibres in the flume increases, while (2nd), the mean roving thickness in the flume zone decreases. Therefore, the proportion (c) in the previous paragraph increases, and will compensate for the lower effective twist rate, to maintain approximately the same degree of coherence.

Backward movement of the unit would have the opposite effect. It may therefore be assumed that adequate coherence is provided in the flume zone at all operative positions of the "unit."

As previously noted, when using the same textile material, the effective twist rate in the front zone depends on draft, initial twist rate of the roving, and the position of the adjustable unit. Increasing the draft decreases the effective twist rate and consequently coherence. To compensate for this by varying the initial twist rate is, as has been stated, not in general desirable. Effective twist rate in the front zone can be varied by moving the adjustable unit, but not

enough to compensate for the large variation caused by change of draft. Two other ways remain by which we can compensate for the coherence loss resulting from draft increase, namely:

(a) Increasing the tension for tensioned fibres (by increasing tension roller leading), and

(b) Increasing the proportion of tensioned fibres (by moving the adjustable unit forwards). Decrease of draft would increase the effective twist rate in the front zone and so require reduction in coherence which could be realized by reverse action to (a) and (b) above.

Method of calculating draft, etc.—By a correct combination of the factors (a), (b), (c) and (d) of the third previous paragraph conditions in the front zone can be provided which will take care of all draft conditions (subject to a dimensional limitation to be referred to hereafter). We can express an equation

$$E \times C \times T \times \frac{P}{N} = K \quad (I)$$

Where

E = effective twist (as previously defined)

C = the limit count for the material,

T =the tension per tensioned fibre,
 P =the number of tensioned fibres,
 N =the number of fibres in the roving,

$\frac{P}{N}$ =proportion of tensioned fibres

K =a constant, dependent on the nature of the fibres.

When this equation is satisfied at the point of minimum coherence (that is to say, the exit from the flume if there is a flume, and otherwise the point immediately forward of the tension rollers), it can be assumed that optimum coherence conditions obtain in the front zone. Properly speaking, the effective twist at any point in the roving depends (as already explained), upon the initial twist, and the condition of the roving, as well as upon the roving cross section at that point and the extent to which the twist has run along the roving. It will be assumed, however that the initial twist is always determined according to the empirical procedure described above, so that the effective initial twist at the time of drafting is always the same. If this is so, E may be regarded as depending only upon the roving cross-section and the running of the initial twist, and so only upon roving cross section and draft; the constant factor representing effective initial twist being allowed for by suitable choice of the constant K . E may then (for reasons which will not be explained here) be taken to be

$$\frac{1}{d^{1.46}(1-Y)}$$

where Y will be Y_f (as defined hereafter) if there is a flume and Y_t (as defined hereafter) if there is none.

Now, from Figure 17 it will be seen that the number of tensioned fibres in the front zone is proportional to the cross-sectional area at the tension roller nip point, shown as BD . Referring now to Figure 13, obviously the greatest roving thickness in the front zone is at the flume exit, this thickness being marked LK in that figure. This is the point where there is the lowest proportion of tensioned fibres to roving thickness. We can therefore say that

$$\frac{P}{N} = \frac{BD \text{ in Fig. 17}}{LK \text{ in Fig. 13}}$$

The upper member of this ratio increases with approach to the drafting rollers, as shown by Figure 17, while the lower member decreases. Therefore, the value of this ratio increases with the forward movement of the "unit."

If the flume were not provided, there would be no flume zone and the front zone would extend from the drafting rollers to the tension rollers. In such case the roving thickness should be taken at the tension rollers (MN in Figure 13), and the value of

$$\frac{P}{N}$$

would then be

$$\frac{BD \text{ in Fig. 17}}{MN \text{ in Fig. 13}}$$

Obviously, this second ratio is lower than the first. The flume exit can always be moved closer to the drafting rollers (by the length of the flume), than the tension rollers. For high draft, the flume therefore gives considerable advantage in raising the ratio of tensioned fibres

to the whole roving thickness when the tension rollers have reached the limit of their forward movement, i. e., when they almost touch the drafting rollers. In cases of relatively low draft, the flume may not actually be required, in theory. As a practical matter, however, its use is of considerable advantage in this case also, since it ensures that the roving leaves the tension rollers in a twisted form, and so prevents fibres from lapping around the rollers.

The extraction area relating to a given quality is always the same shape, irrespective of draft. We can make the greatest ordinate equal to 1, and then use the values of the vertical ordinates to ascertain the thickness of the whole roving or the front fibres only at any point along the draft zone at any draft. Such an extraction area is shown in Figure 18, with the tension rollers and flume shown diagrammatically in the position for a draft of 40. The vertical ordinates of the curve in general are termed Y .

It has been found that the cross-sectional area of the whole roving at any point along the draft zone, at any draft, is $R(1-Y)$, where R =drams per 40 yards of the initial roving.

Also, the cross-sectional area of the front fibres, in drams per 40 yards at any point along the draft zone,

$$= \frac{RY}{d}$$

where d is the draft.

Calling the Y ordinates at the tension rollers= Y_t , and those at the flume exit= Y_f , the roving thickness at flume exit is $R(1-Y_f)$, and the front fibre thickness at the tension rollers if

$$= \frac{RY_t}{d}$$

Therefore, when using a flume, the proportion,

$$\left(\frac{P}{N} \right)$$

is

$$\frac{RY_t}{d} : R(1-Y_f)$$

that is, equals

$$\frac{Y_t}{d(1-Y_f)} \quad (ii)$$

and when not using a flume, is

$$\frac{Y_t}{d(1-Y_t)}$$

55 T may be taken (for reasons already explained) as being proportional to the deadweight loading upon the top tension roller.

Setting out Equation I again for convenience:

$$60 \quad \frac{ECTP}{N} = K \quad (\text{a constant relating to the textile material being drafted})$$

We substitute for the above symbols the values derived above and the equation becomes:

65 When using a flume

$$\frac{1}{d^{1.46}(1-Y_f)} \times C \times T \times \frac{Y_t}{d(1-Y_f)} = K$$

or

$$\frac{CTY_t}{d^{2.46}(1-Y_f)^2} = K \quad (iii)$$

or, when not using a flume,

$$\frac{CTY_t}{d^{2.46}(1-Y_t)^2} = K \quad (iv)$$

Providing the above Equations iii and iv are satisfied, for the flume and flumeless cases respectively, optimum coherence and fibre control conditions will exist in the front zone, and, if a twist stabilizer is used in the back zone, the front zone is the only one we need trouble about.

The appropriate draft, d , for the given conditions can now be obtained by transposing the above equations, as follows:

When using a flume

$$d = \sqrt{\frac{CTY_t}{K(1-Y_t)^2}} \quad (v)$$

and, when not using a flume

$$d = \sqrt{\frac{CTY_t}{K(1-Y_t)^2}} \quad (vi)$$

Calculations of adjustments.—As stated earlier, the distance between the feed and drafting roller nip points in the process herein described should always exceed the length of the longest fibre. Means should therefore be provided for adjusting the distance between feed and drafting rollers for this purpose as is common.

A usual length for a flume, with the apparatus described, is 0.75 inch, measured from tension roller nip point to flume exit. This length is determined by the consideration that it should be such as to cause the flume exit and tension rollers practically to touch the drafting rollers at the same time, when the adjustable unit is moved to its most forward position. If the tension rollers can be so constructed as to be able to move closer to the drafting rollers, the flume can be made shorter. With the apparatus described, the most forward tension roller nip point setting is 1.25 inches from the drafting roller nip point.

Analyzing the functions in Equations v and vi above, we see that (a) C (limit count) depends on the thickness of the fibres; (b) K depends on the general properties of the material being drafted:

$$(c) \frac{Y_t}{(1-Y_t)} \text{ and } \frac{Y_t}{(1-Y_t)}$$

depends on (1) the length analysis of the fibres and (ii) the tension roller setting; (d) T depends on the deadweight actually applied to the top tension roller, which must be limited by the tensile strength of the fibres.

We see that among these, only (c) (ii) and (d) are within the control of the operator, and provide the means of adjustment the others all relating to the type of material being drafted and therefore serving to set the problem to the operator. Therefore, only two adjustments of the mechanism are required, namely, movement of the adjustable unit back and forth (variation of tension roller setting), and variation of the deadweight applied to the top tension roller. In addition, the most suitable initial twist rate should be provided, which is best determined by empirical methods, as explained above, and the most suitable roving thickness must be determined, as will be explained.

Tension roller setting.—Equations v and vi above show that the higher is the value of

$$\frac{Y_t}{(1-Y_t)^2}$$

or

$$\frac{Y_t}{(1-Y_t)^2}$$

the higher will be the appropriate draft, all other factors being equal. Figure 18 shows that these

values are increased with decrease in tension roller setting, with their maximum possible value at the minimum tension roller setting. From Figure 18 we can read off the Y_t value for this minimum setting as the length of the vertical ordinate 1.25" distant horizontally from the drafting roller nip point. This value is 0.28. The Y_t value is the vertical ordinate at a horizontal distance of 0.5" (i. e., 1.25" less 0.75" flume length) from the drafting roller nip point; its value is 0.62. From this, we can calculate that in the flume case,

$$\frac{Y_t}{(1-Y_t)^2} = 1.94$$

and in the flumeless case,

$$\frac{Y_t}{(1-Y_t)^2} = 0.54$$

We can further determine that the ratio:

$$\frac{\text{Maximum draft with flume}}{\text{Maximum draft without flume}} = 1.68$$

which indicates that an increase in draft of about 70% can be obtained when using a flume, in comparison with the omission of the flume. This value only applies, of course, to the particular wool quality (64's/70's wool) to which Figure 18 refers.

It will now appear that it is possible to plot tension roller setting curves, for the different qualities of material, which will be useful. For the sake of convenience, we will abbreviate by letting

$$\frac{Y_t}{(1-Y_t)^2}$$

in the flume case = Z_f , and

$$\frac{Y_t}{(1-Y_t)^2}$$

in the flumeless case = Z_t .

For 64's/70's quality of wool to which Figures 13-18 all refer, the following data applies:

$$C = 52.5$$

45 $T = 7.25$ oz. (this figure has been found to give a satisfactory margin of safety against fibre-breakage due to overstressing, in all standard wool qualities)

$K = .00712$ (this figure has been found satisfactory for all standard wool qualities, but (as already explained) the figure to be taken depends upon the precise procedure adopted for determining the amount of initial twist to be put into the roving).

55 By substitution in Equations v and vi above we get

$$\text{Flume case } d = \sqrt{53530 Z_f} \quad (vii)$$

and

$$\text{Flumeless case } d = \sqrt{53530 Z_t} \quad (viii)$$

We can now read off the Figure 18 curve the Y_t and Y_f ordinates for different tension roller settings, starting with the minimum distance of 1.25" and going down to (say) 3". The Z_f and Z_t values for the flume and flumeless cases respectively are then calculated and substituted in Equations vii and viii above. This will give the value of d for the different tension roller settings. We then plot d against the tension roller setting for which the Z_f and Z_t values obtain in each of the flume and flumeless cases, and get two curves which show us the maximum draft obtainable (at minimum tension roller setting), and the opti-

mum tension roller settings for all drafts below the maximum.

Two such cases relating to the flume and flume-less cases respectively are shown in Figures 19 and 20, and are marked A in each case. From these it appears that the maximum drafts for the 64's/70's wool quality are:

With flume 110.

Without flume 65.

Deadweighting of top tension roller.—The maximum value of T is limited by the tensile strength of the fibres being drafted. As stated, a reliable value in the case of wool has been found to be 7.25 ozs.; alternative weights are supplied for the purpose of varying T . It is my belief that empirical methods are best in this case as well as in the fixing of the initial roving twist, discussed above; this is for the reason that there are many factors which can cause unforeseen variations in the tensile strength and the effective twist of wool fibres. Any variation in weighting is therefore best left, in mill conditions, to a qualified man on the spot.

Maximum roving thickness which can be accommodated.—A design of flanged tension rollers such as is the preferred construction herein imposes a limitation on the size of roving which can be used. In the design particularly considered herein the tension roller cannot deal with a roving any thicker than 55 drams per 40 yards, because of the limited space between the rollers and the flanges. Conditions, therefore, must be such that at a distance from the drafting roller nip point equal to the tension roller setting, the roving must not exceed 55 drams per 40 yards. Usually, a range of counts of yarn will be required from a given roving of a certain thickness. Naturally, on economic grounds, the maximum draft obtainable from the textile material, and the machine, would be desirable.

Suppose, therefore, a roving is prepared to produce the finest count at maximum draft; in this case the tension rollers will be in their fully forward position and the thickness of roving between them will be relatively thin because of the roving taper in the draft zone. Now suppose that the coarsest count of the range is required; this will call for a lower draft and a consequent backward movement of the tension rollers because of the high value of tension roller setting appropriate to the lower draft. The roving thickness between the tension rollers will now be thicker because of this movement up the taper of the roving; indeed, the thickness of roving may exceed the maximum of 55 drams per 40 yards. Thus, the roving will not cover the coarsest count of the required range. Suppose, therefore, the initial roving is made much thinner to guard against overloading of the tension roller in the coarse count conditions, it might be made so thin that it is well under the 55 drams per 40 yards limit, and in addition will not allow for anything like the maximum draft when spinning the fine count. The problem is, therefore, to fix the initial roving thickness so that the count range obtains the highest draft for the finest count without overloading the tension rollers when producing the coarsest count.

For the above reasons, the fixing of initial roving thickness by empirical means is tedious, involving making a number of different rovings to be tried at various drafts according to the range of yarn counts to be produced. This difficulty can however be overcome by resorting to a graph-

ical method. So far as worsted spinning is concerned, a simple formula, which is in general use, can be utilized, this connecting draft, roving thickness, and yarn count.

5 If R is the initial roving thickness in drams per 40 yards, and d =draft, and y =the worsted counts of the yarn to be spun, then

$$(a) \quad \frac{R}{d} = \frac{18.3}{y}$$

or

$$(b) \quad R = \frac{18.3d}{y}$$

or

$$(c) \quad d = \frac{R_y}{18.3}$$

or

$$(d) \quad y = \frac{18.3d}{R}$$

Let us take the value of y to be 10 which will be used as an index count; now calculate the value of the roving thickness (R) to produce 10's counts at drafts shown on curve A in Figures 19 and 20. Equation b above shows:

$$R = \frac{18.3d}{10}$$

or

$$R = 1.83d$$

R is plotted against D in Figures 19 and 20. These curves (which are straight lines) are marked B in both figures. Now calculate the thickness of the roving at the tension roller setting position along the roving, taking R as the initial roving thickness. The tension roller setting for this purpose is the same value as the tension roller setting of curve A at the same vertical ordinates as the R value selected. The value of the roving thickness at the tension roller will be this tension roller setting value of $(1-Y_t)$ from Figure 18 multiplied by R (i. e., $R(1-Y_t)$). Plot this value against the draft value of the R selected. When this has been done for several R values, a curve can be plotted; such curves are shown in Figures 19 and 20, and are marked C. We now draw a horizontal line through the 55 drams per 40-yards ordinate. The R value which will load the tension roller to 55 drams when producing 10's counts is vertically above the intersection of curve C and the horizontal 55 drams line. R is shown on both Figures 19 and 20 as 60 drams.

These B and C curves can be used for finding the maximum value of R for counts other than 10's; for example, suppose a yarn no coarser than 20's is required. Multiply

$$55 \text{ by } \frac{20}{10} = 110$$

Draw a horizontal line in Figure 19 through the 110 drams ordinate and note the point of intersection with the C curve. Note also the value of R vertically above this point of intersection (142 drams) and multiply it by

$$\frac{10}{20}$$

the result (71 drams) is the initial roving thickness which will produce 20's counts with full loading of the tension roller (i. e. 55 drams per 40 yards). The draft to produce 20's in this case must not, of course, exceed the maximum draft. This can be prevented by drawing a vertical line up to the maximum draft ordinate and not plot-

ting B and C curves beyond this line. If 55 is now multiplied by too great a factor the C curve will not rise high enough to meet the horizontal line drawn through the product, showing that the consequent draft would be greater than the maximum.

Limitations of draft.—From the above discussion we see that there are two mechanical limitations to draft, viz.,

- (a) the minimum value of the tension rollers setting when spinning fine counts, and
- (b) the loading of the tension roller when spinning coarse counts.

There are also three limitations to draft exercised by the textile material itself, viz.,

- (c) The Z_f and Z_t values.
- (d) The limit count.
- (e) The textile strength of the fibres.

In some cases, limitations (d) and (e) can be offset against each other, because low limit count indicates coarse fibres, which should have a greater tensile strength, and so withstand a higher value of T.

Adjustments of machine in practice.—Suitable tension roller settings, i. e., distances from the drafting roller nip point, to obtain optimum results for various conditions as explained above, can be found by trial and error. It is thought however that the best method is to calculate a setting, as explained above, and then make the final adjustment by trial and error according to the standard of yarn being produced. The mechanism for altering the tension roller setting, which will now shortly be described, preferably incorporates a dial showing accurately, to two decimals, the inch measurement of the tension roller setting, any alteration to this setting being made while the machine is running, by turning a handle.

Further description of apparatus.—An addition will now be made to the description of apparatus given in the early part hereof, to complete the showing of a commercially-operated machine. In the course of this, special attention will be given to the design of the flume, and of the drafting rollers, both of which involve novel features of importance.

Suitable feed rollers are shown, in end view, in Figure 21. As has been stated above, the usual cylindrical feed rollers tend to flatten the roving into the form of a ribbon, and this tends to prevent the initial twist in the roving from passing through the nip of these rollers, with the result that this twist tends to "build up" between the feed rollers and the supply bobbin. The effect of this is to cause an intermittent flow of twist, which has undesirable effects on the drafting operation and the finished yarn.

This difficulty is substantially avoided in the construction illustrated. A series of lower rollers 3 are shown as formed on a shaft 3a, each roller being formed by a fluted barrel portion 3b, and a pair of spaced collars 11, the faces of which constitute a pair of flanges between which the upper rollers 2 fit closely. The upper rollers 2 are spring loaded to the extent necessary to feed the roving 1 forward, pressure being applied to the upper rollers by means of a spring loaded spindle 46 passing through a web 47 of the supporting bracket 48 secured to a support 49. Spindle 46 is surrounded by a spring 50, a slotted member 51 being freely mounted on the spindle and arranged to embrace the shaft 2a to which the up-

per rollers 2 are secured in pairs. The spring pressure is adjusted by means of a wing nut 52. The edges of the grooves in rollers 3, into which the upper rollers 2 fit, are preferably flared, as shown.

The detachable unit.—The adjustable unit, as stated earlier above, is preferably a detachable construction, adapted to be separately made and supplied to spinning mills, where desired, to aid in converting existing apparatus to the use of the process herein described. The partial description of such a unit, given in connection with Figure 1, will now be somewhat amplified, reference being made to Figures 22-27, it being understood that the unit will be the same as described, with the omission of the flume, if the process is carried out in the "flumeless" manner described above.

Figure 22 shows a sectional elevation of the unit, similar to that shown in Figure 1, but with a "twist stabilizer" additionally carried thereby. The unit as a whole is indicated by the reference character U. As stated in connection with Figure 1, the main framework 13 of the unit is formed with a semi-circular bearing surface arranged to rest on the upper surface of bearing member 19, forming part of the drafting apparatus, the bearing member being secured to the supporting bar 38.

The lower roller 6 is formed on a shouldered shaft 54 rotatably mounted in bearings 55 arranged in open-topped apertures 56 in the framework 13, the bearings making a light push fit with the apertures 56. The shaft 54 is tapered inwardly to such a diameter that upon withdrawal of the shaft in an axial direction it can readily be removed from the unit, the shaft being drawn clear of the bearing 55 at one end while the bearing 55 at the other end is drawn out of the aperture 56 by the adjacent shoulder on the shaft 54 to allow the tapered portion of the shaft to be lifted clear of the adjacent open-topped aperture 56.

A gear 16 is secured to one end of the shaft 54 and is driven from gear 17 on driving shaft 18 through gear 14 on countershaft 26 mounted in the framework 13. A gear 24 mounted on the other end of shaft 26 drives the upper roller 5 through an idler gear 27 and a gear 28 secured to the adjacent end of the roller 5.

The upper roller 5 is rotatably mounted in supporting bracket 21 pivoted at 22 on the framework 13 in such a position that as the bracket 21 is swung outwardly to the "open" position the gear 28 is caused to rotate to some extent around the idler gear 27 as it moves out of engagement therewith. The bracket 21 is shown in Figure 23 in the open position in full lines and in the closed position in chain-dotted lines. The upper roller 5 is preferably fluted, and formed on an inwardly tapered shaft 57 similar to the shaft 54 which is shouldered at the ends to form journals by which the shaft is rotatably mounted in bearings 58 arranged in open topped aperture 59 in the bracket 21. The shaft 57 can thus readily be removed from the bracket 21 by an axial and radial movement similar to that described above with reference to shaft 54. Removable weights 23 are secured to the bracket 21, as earlier described, for supplying the necessary pressure to the roving, a number of alternative weights being provided.

The roving guide 4 is shown as formed with a pair of tongues 60 by means of which it is slidably mounted in a pair of slots 61 formed in the

framework 13 and is retained in the slots by means of a spring-loaded ball 62 housed in the framework 13 and arranged to engage a recess formed in one of the tongues 60.

The "flume" 7 may be formed with a pair of extending feet 63 by which it is supported in a pair of slots 64 formed in laterally extending portions 65 of the framework 13. The flume is retained by a pair of leaf springs 66 secured to the frame portions 65 and bearing on the feet 63. The flume is preferably arranged in alignment with the groove of the lower roller 6 by means of a lug 67 projecting from the base of the flume and bearing between the flanges of the lower roller, the tip of this lug also bearing on the cylindrical surface of the roller so as to act as a scraper. The channel of the flume is, in the form shown particularly in Figure 27, provided with side walls 68 and a bottom 69 providing three surfaces against which the roving will engage.

As previously mentioned, the "twist stabilizer" 7A may be positioned wherever it is needed in the back zone. I have, however, found it convenient to mount the twist stabilizer in the position and manner indicated in the drawings. Thus, the twist stabilizer 7A as indicated in Figures 22, 24 and 28, is similar to the flume 7 in construction, except that it has a wider and deeper channel, since it engages a thicker part of the roving than does flume 7. Also, its channel is preferably a deep V shape, as is shown in the front view of this member, Figure 28, and it has a flat bottom 70 which normally rests on the flat transverse surface 71 of the frame structure 13. Twist stabilizer 7A is positioned on this surface with its flat front end 72 foremost, abutting against the rear of the roving guide 4. In this position the outer side surfaces of stabilizer 7A will fit loosely against the side surfaces 73 of the cheeks 74 which constitute part of the side walls of the construction.

The twist stabilizer therefore simply rests in the space between cheeks 74 which therefore prevent it from rotating, while it is restrained against forward movement by the roving guide 4. The roving passes through the stabilizer, and is prevented from rotating throughout the length of this member thereby. The unit is tilted downwards towards the front, as is shown in Figures 1 and 22, and therefore the stabilizer is held against upward or rearward movement, while the apparatus is in operation, by the combined action of the roving, pressing downwards and dragging forwards, and gravity.

The preferred manner of securing the unit to the apparatus is shown in greater detail in Figures 22 and 25 than in Figure 1, in connection with which it was briefly described. The unit, as shown in Figures 22 and 25, is secured to the apparatus by means of a pair of pins 32 slidably mounted in the frameworks 13 and arranged to engage a corresponding pair of holes in a saddle member 31a. The pins 32 are actuated by a pair of leaf spring members 33 secured at 75 to the frame 13.

The saddle member 31a is secured to a pair of rods 34a and 34b which are slidably mounted in the extension 36 of the bearing member 19 to allow the unit to be traversed bodily, the rod 34b being common to a series of units, identical with the one described, and provided with traversing mechanism.

When used in a spinning frame of the kind normally used for the drafting and spinning of worsted rovings, one unit of the character de-

scribed is provided for each spindle on the frame, and it is intended in this example to mount the units in sections, each of eight units, as is illustrated in Figure 29, a support 38 being provided for each section. A bearing member 19 is provided for each unit, and the two end bearing members in each section serve as bearings for a common driving shaft 18 to which is secured a series of gears 17 for driving the top and bottom rollers 5 and 6 of the units. The gears 17 are preferably arranged between the bearing members 19 with each gear 17 serving to drive the rollers of two units. The various driving shafts 18 for the various sections are connected by couplings 16 one end shaft being connected by suitable gearing to a driving member on the spinning frame.

As is shown in Figure 29, the supports 38 of each section are secured by bolts 36A to brackets 41A, slidably mounted on tubular supports 42, mounted in upper and lower brackets 81 and 82 secured to the framework 83 of the spinning frame. The brackets 41A, though performing the same function as the brackets 41 described earlier, are of slightly modified shape, and are connected through slots 85 in the tubular supports 42 to chains 84 and by those chains to brackets 86 which are attached to a common adjusting rod 87 which extends along the length of the spinning frame. This rod 87 is supported on rollers 88 carried by the brackets 81.

In the section illustrated in Figure 29, the adjusting rod 87 is divided for the insertion of a worm and wheel unit 89 mounted on a supporting bar 91 which is secured to the adjacent pair of brackets 81. The unit 89 co-operates with a screw-threaded shaft 92 attached to the divided ends of the rod 87. Upon operation of the unit 89, by means of a crank 93, the screw-threaded shaft is moved axially thus causing the rod 87 to move the section of eight units U together with their common driving shaft 18 and traversing shaft 34, towards or away from the nip of the drafting rollers, according to the direction of rotation of the crank 93. An indicator 94 is incorporated in the unit 89 by which the distance of the units U from the nip of the drafting rollers can be read.

The indicating device and its connections are shown in Figure 30. It will be seen that the screw-threaded shaft 92 secured to the adjusting rod 87 is mounted in the screw-threaded bore of a worm wheel 95 which is rotatably mounted in the casing 96 of the worm and wheel unit 89. Shaft 92 is prevented from axial movement by an abutment 97 and a thrust bearing 98. The worm wheel 95 engages a worm 99 rotatably mounted in the casing 96, the crank handle 93 as shown in Figure 29, being secured to the shaft of worm 99. Secured to the worm wheel 95 is a gear 100 connected by gearing 101 to a measuring device of known construction and generally indicated by reference numeral 102. This device is calibrated in terms of the distance of the nip of the intermediate rollers 5, 6 from the nip of the drafting rollers.

Flume design.—Two particular matters remain to be discussed, namely, in relation to the "flume," and to the drafting rollers. The function of the flume is to prevent rotation of the roving over a distance equal to the length of the flume, and this effect is brought about by the provision of surfaces which operate to deform the cross-section of the roving in such a manner that it cannot rotate without substantial further de-

formation. Preferably, the roving is passed through a channel having a horizontal bottom and two vertical sides, the sides being closer together (as will be further explained hereinafter) than the diameter of the undeformed roving. Such a channel is illustrated in the accompanying drawings. Alternatively (as in the case of the twist stabilizer 7A) a V-shaped channel may be used, the included angle at the apex of the V being small—say 30°. In speaking of a "channel shape" in this specification I mean to include both these forms, and any other cross-sectional shape having two suitable side walls and provide further that either the flume channel has no top (as is indicated in the showing of the "twist stabilizer" 7A), or if a top is provided, the depth of the channel must be great enough to permit the roving to deform upwards, without contacting the top. With this provision, overloading of the channel will not cause the roving to stick in the flume. It will also be noted that one type of flume will cover a large range of roving thicknesses, since, with the design of flume indicated, there need be no closely controlled relationship between the unrestrained roving diameter and the flume channel width.

In this connection, it is noted that a top of the flume 7 (as shown in the drawings, with a narrow central, lengthwise slit therethrough), while not necessary from the anti-rotation point of view, is of some value as performing the function of the "trumpets" and "condensers" known in the art, i. e., that of preventing undue dispersion of the fibres which normally stick out of a roving. It prevents these fibres from being seized by the drafting rollers at a point out of line with the main roving. If this happens, the stray fibres are drafted away from the core of the yarn, and cannot get twisted into the yarn as they emerge from the drafting rollers.

Some instructions will now be given for ensuring that a flume of given dimensions will be suitable for given roving conditions. These instructions are phrased in terms of compression of the roving, since this enables a convenient form of calculation to be adopted. It will be understood however that this "compression" is predominantly notional, the figure given for "compression" serving as a measure of the degree of deformation of the roving that will occur.

The so-called Ashenhurst's Rule is well known in the textile industry for ascertaining the diameter in inches of any count of yarn. Applying this to rovings, by calculations which need not be repeated here, we find that

$$A = \frac{R}{10560} \text{ approximately}$$

where

A =cross sectional area of roving in square inches,
and

R =roving thickness in drams per 40 yards.

Ashenhurst's Rule applies to tightly-twisted yarn, which means that the compression in cross section is high, and the value of A in the above equation assumes a roving which is highly compressed in cross section. I have ascertained experimentally that, if rovings are laid between the flanges of the bottom tension roller and subjected to the pressure imposed by the top rollers carrying a weight of 7.25 oz., which as previously stated, is approximately 70 lbs. per square inch, the experimental value of A is almost identical with the value of A obtained from the above equa-

tion. I will therefore use tension roller compression as the index of compression required by this equation. Thus I will speak of the degree of compression being halved, if the cross-sectional area is doubled, so that for "half tension roller compression" the cross-sectional area of the roving will be $2A$.

If a roving of circular cross section is deformed to a square shape but of the same cross sectional area as the circular shape of the unrestrained roving, pressure will be caused between the flume channel and the roving periphery, and we will take the deformation resulting from this change of shape as an index of deformation. When the roving is thus deformed into a square, if s is the length of each side, then

$$S = \sqrt{A}$$

Figure 31 shows two curves, one marked X which represents $\sqrt{A}$ or S plotted against R with full tension roller compression, while the curve Y represents $\sqrt{2A}$ or $1.414S$ plotted against R with half tension roller compression.

In this type of flume in general use in the process herein described, the width at entry is 0.075" and 0.25" deep, the exit end being 0.065" wide and 0.075" deep. Width is what gives the pressure, depth being to allow for increased loading. In Figure 31 vertical ordinates are drawn at 0.075" and 0.065" representing the width of flume at entry and exit respectively. These ordinates cut curves X and Y at C, D, E and F. Roving thickness (drams per 40 yards) can be ascertained at flume exit and tension roller nip point, which is approximately the same as flume entry. Thus, roving thickness at

Flume entry = $R(1 - Y_t)$ drams per 40 yards
Flume exit = $R(1 - Y_f)$ drams per 40 yards

The $R(1 - Y_t)$ value is plotted, in any given case, on the flume entry ordinate opposite the appropriate roving thickness ordinate, as shown at the left, and, similarly, the $R(1 - Y_f)$ value is plotted on the flume exit ordinate. Both plots are now joined by a line and, as has been demonstrated in practice, if the line lies in area CDEF, then the flume exit will fit the roving conditions and the anti-rotation effect will exist.

One qualification should however be noted. For fine count spinning both these plots should lie close to F and E, since the feeding force is low under these conditions and too much contact pressure between the roving and the channel would cause the roving to stick in the flume. For spinning thick counts, such as 10's so long as the $R(1 - Y_t)$ and $R(1 - Y_f)$ values lie just below C and D the high value of the feeding force will pull the roving through the flume.

If it is desired to design a flume channel for a special roving case this can easily be done by reference to Figure 31. It will be necessary to plot the $R(1 - Y_t)$ and $R(1 - Y_f)$ values on such vertical ordinates as will bring them to an appropriate level between the X and Y curves. The righthand ordinates will give the value of the flume entry width and the left hand ordinate will give the flume exit width.

As to the length of the flume, it must be long enough to provide a sufficient area of contacted length of roving to prevent rotation, and it must not be too long or the resistance to the feeding force will be too great. Anything between 0.5" and 0.75" seems satisfactory. If the above conditions are satisfied, the ideal length is such as to fill up the distance between the tension rollers

and the drafting rollers, when the tension rollers are as near to the drafting rollers as they can be without touching them.

Drafting roller design.—Drafting rollers operating under conditions of high draft present problems which are not present or are not important, when operating under low draft conditions and consideration of drafting roller design for high draft will constitute the last topic herein. Observance of the principles which will now be explained will produce greatly improved results.

I will first examine the points in which conventional drafting roller design may lead to defective results when operating at high draft. The 15 taper of the roving from the drafting roller nip point to a point (say) half an inch backwards is much greater in high draft than in low draft conditions. The taper can be considered from the standpoint (a) of cross sectional area thickness taper and (b) diameter taper. By way of example, suppose a yarn is spun to 36.6's worsted counts, which is equivalent to $\frac{1}{2}$ dram per 40 yards. We will consider two cases.

In case 1 the draft is 6, with an initial roving 25 of 3 drams per 40 yards.

In case 2 the draft is 100 with an initial roving of 50 drams per 40 yards.

The first point to be considered is the increased 30 irregularity of yarn produced, when the drafting roller nip point has a slight temporary horizontal movement, at high draft, in comparison with the same slight movement at low draft.

Figure 32 shows the draft zone diagram of cases 1 and 2 plotted to a distance of 0.6" back from the drafting rollers. The vertical ordinates show the thickness of the roving, in drams per 40 yards, at different distances from the drafting roller nip point. Comparison of these curves shows the greatly increased cross-sectional area taper in case 2 in comparison with case 1. On calculating the roving thickness in case 1 and case 2 respectively, at a distance of 0.025" from the drafting rollers, we find this to be 0.556 dram per 40 yards in case 1, and 6.188 drams per 40 yards in case 2. Therefore, a temporary horizontal movement of the drafting roller nip point, a distance of 0.025" nearer the feed rollers, would cause the drafting rollers to grip the roving at a point where it is thicker and so increase the yarn thickness. In case 1, it can be calculated, the increased yarn thickness due to this movement would be 11.2%, while in case 2 it would be 239%. Considerable yarn irregularity would therefore be caused by variations of the drafting roller nip point, back and forth, by small amounts such as 0.025", in case 2, that is, at high draft, and it is evident that the provision of a more nearly fixed drafting roller nip point is much more important at high than at low draft. This effect of causing yarn irregularity by varying drafting roller nip point position will be referred to as "nip point effect."

Figure 33 shows the diameter of the roving, in inches, at any distance from the drafting rollers, up to 0.6", for cases 1 and 2, the two curves shown being calculated from the curves in Figure 32. (The angles $Ta1$ and $Ta2$ in these figures are shown of exaggerated magnitude for clarity of illustration by taking coordinates on different scales.) The angle of diameter taper up to a point 0.1" distant from the drafting roller nip point is marked in Figure 33 as $Ta1$, for case 1, and $Ta2$, for case 2. It can be shown that angle $Ta1$ is $1\frac{1}{2}^\circ$ approximately, and angle $Ta2$ is $10\frac{1}{2}^\circ$

approximately. The much greater angle in case 2 has two effects. First, the yarn, which is of the same thickness in both cases, is flattened by the pressure of the drafting rollers into a ribbon. It can be seen that the width of the ribbon in case 2 is likely to be much greater than in case 1, and therefore the dispersion of fibres is much greater in case 2, since the number of fibres is the same in each case. This means that in case 1 the drafting rollers have a fairly compact bundle of fibres to grab, while in case 2 they have almost to grab each fibre individually, which may not always be accomplished. The above will be referred to as "fibre dispersion effect."

Secondly, the peripheral arcs of the top and bottom rollers approach gradually towards each other until they meet at the nip point. If these arcs touch the roving for an appreciable length before they grab it at the nip point, they will act 20 in similar manner to the flume in preventing rotation, and this will maintain the initial twist rate of the roving, and may well lock the fibres together and prevent the drafting rollers from grabbing individual fibres as they are presented. This will be referred to as "twist effect." Comparison of the angles $Ta1$ and $Ta2$ shows that the angle of approach of the peripheral arcs of the top and bottom rollers must be greater than $1\frac{1}{2}^\circ$ in case 1 and $10\frac{1}{2}^\circ$ in case 2 (high draft), to prevent the described difficulty.

For one further point, the degree of acceleration on a front fibre at the instant of grab by the drafting rollers is directly proportional to draft. The stagger interval of fibres (the overlap in length of one fibre beyond another), approaching the drafting rollers is much smaller in high draft than in low, the stagger interval varying inversely as draft, approximately. For these reasons, a much more precise and instantaneous grabbing action by the drafting rollers is required for high draft. This will be referred to as "grab action."

The above considerations are pertinent for the reason that the action of drafting rollers commonly now used in drafting worsted is insufficiently uniform fully to meet the above requirements, there being, among other defects, too great a variation, horizontally, in the drafting roller nip point.

50 The "nip point" and "twist effect" difficulties can be much reduced by causing the approaching peripheral arcs of the top and bottom rollers to meet at the nip points in such a manner that the tangents to the arcs at the nip points subtend an appreciable angle, which will be referred to as the "angle of incidence." It must be greater than the angle of the diameter taper to prevent "twist effect."

60 The required angle of incidence can be provided by using a cover on one of the drafting rollers, say the top roller, which is radially compressible and is softer than is customary for such roller covers, and by providing a suitable pressure between the rollers. This softness will cause this roller to be depressed over its arc of contact with the other, hard, roller, such a depression being shown in Figure 34.

Figure 35 shows curves A and B; curve A shows the angle of the contacted arc of the bottom (hard) roller for various depression values, while curve B shows the angle of incidence for different depression values. For drafts of 100 or so a depression of 0.025 to 0.03, with a constant angle of incidence of about 14° has been found satisfactory to overcome the "twist effect."

Nip point effect is also reduced by increasing the angle of incidence and the depression. It can be shown that with a depression of 0.001" a variation of 0.001" in depression would cause 0.017" horizontal variation in nip point, while with a depression of 0.03" a 0.001" variation in depression only causes 0.004" horizontal variation in nip point. Therefore the use of an angle of incidence of about 14° would largely remedy this nip point variation difficulty. It should be realized that, in the usual commercial practice, variations in depression of the softer roller, as great or greater than the 0.001" mentioned above have been universal and that it is not commercially practical to avoid them, with the known constructions. The figures given above relate, of course, only to the sizes of rollers shown in Figure 34, namely, 3 1/4" diameter for the top, soft, roller and 4" for the bottom roller.

Properties required in top roller covers.—The top roller should be soft, radially compressible, and resilient to allow for the depression, and it has been found that the range of softness for optimum conditions normally lies between 55 and 75 degrees of hardness as given by the Shore Durometer, this being considerably softer than the top roller covers commonly used, the pressure between the rollers being adjusted to produce the desired depression in the soft cover. In certain cases, hardness between 75° and 80° may however be preferable, a considerably greater pressure than is customary then being applied. Radial compressibility of the top roller is essential for the best results, since otherwise the depression can only be obtained by circumferential displacement of the material of the cover. This would cause the cover to swell at a point adjacent to the nip point, and so prevent the required angle of incidence from being provided. This is shown, in exaggerated form, in the diagram, Figure 36.

So far as my present knowledge goes, only those materials, generally speaking, which contain air cells, are truly compressible. Cork covers, of suitable softness, and so made as to have uniform resilience all around the periphery, are suitable. Both top and bottom rollers must also run true.

Improved drafting roller construction.—The fibre dispersal effect described above increases the difficulties caused in providing a grabbing action for the drafting rollers which will be efficient in view of the greater fibre acceleration and selectivity inseparable from high draft. The instantaneous grabbing of a single fibre tip is difficult enough, but once seized, it must be let go immediately it emerges from the front side of the nip point. A high coefficient of friction of both top and bottom rollers is necessary, but that alone is not enough. Any slight slip at the moment of grab digs the fibre into the soft cover so that it is not released at the right time, and wraps itself around the roller. This is known as "roller licking" and is a serious fault.

This difficulty is overcome by cutting flutes in the metal (bottom) roller so that the width of the flute is approximately equal to the lands between the flutes. Since the top roller is soft, these flutes impress teeth in the top roller, which bend the fibre tip around the edges of the flutes. The fibres, therefore, actually cause indentations in the top cover teeth and are locked, in effect, in a double bend. When the fibre emerges from the front of the nip point the reverse happens, the teeth in the soft roller disappear and the

fibre is unlocked. This construction and effect are indicated in Figure 37, where the cover 101 of the upper roller is shown diagrammatically with indentations 102 formed by the flutes 103 formed in the hard lower roller. In a preferred embodiment, the flutes are formed by cutting V-shaped grooves 0.04 of an inch wide and 0.008 of an inch deep and having an included angle of 130°. The diagram shows how the fibres 104 are caused to bend around the tips of the flutes 103 as they pass through the drafting rollers.

The mechanical grab and release action described requires several provisions for its perfect working. (a) The edges of the flutes must be clear cut without any roughness on them to hook the fibres. Also, they must be slightly unevenly spaced to prevent periodicity and consequent marking of the top roller. (b) The skin of the top roller cover must not be so soft that the teeth formed by the flutes are too flimsy to hold the fibres. (c) The top roller cover must not have an affinity for oil or grease out of the wool (when wool fibre is being drafted). (d) The skin of the top roller cover must not be smooth since, if it is, a seal will be formed around the indentation made by the fibre in each formed tooth of the cover. Air will be unable to get behind the fibre so that it will stick by suction to the cover and will not be released, resulting in roller licking.

Roller covers made of bonded ground cork, having the properties described above for the soft roller cover, have given excellent results.

In order to ensure the best working conditions, the top rollers should also have the following mechanical properties: (a) Each roller should run on its own individual bearing. Rollers coupled in pairs (a common practice in the past) cause slip if either of them (or the bottom rollers) are different in diameter. (b) The bearings should be of low friction type, e. g., ball or roller bearings. (c) The method of pressure application must be such that there is little friction opposing the rise and fall of the roller centres.

As shown in Figure 38, pressure is applied to the nip of the drafting rollers 8 by a spring-loaded pressure-applying device consisting of an arm 105 pivoted at 106 in a bracket 107 attached to framework 108, a rod 109 of square cross-section extending from the arm 105 and supporting a slidable pressure-applying tongue 110 formed with a depression 111 arranged (in the operative position) to engage the upper roller shaft 112. Near the upper extremity of the rod 109 is slidably mounted an abutment member 113 formed with a spigot 114 between which and a similar spigot 115 on the tongue 110 is arranged a compression spring. The spring pressure is adjusted by means of a knob 117 which makes threaded engagement with a threaded portion 118 of the rod 109. Pressure on the rollers is released by pulling the knob 117 forwardly to disengage the tongue 110 from the shaft 112 as indicated by chain-dotted lines in Figure 38.

What I claim is:

1. A process of single stage drafting textile fibres of the kind in which a roving is forwardly urged at an intermediate point of its length extending between a feeding point and a drafting nip, said process comprising applying a single stage draft of at least 20 to a roving having a predetermined initial twist rate, causing twist to pass continuously through the urging point with the roving from the back zone into the front zone, into which zones the roving has been divided by

the urging point, thus maintaining substantial constancy of twist conditions in both zones, sensible rotation of the roving about its own axis being prevented at a region which at least includes the urging point, the rate of twist in the front zone falling abruptly to its lowest degree in the drafting operation immediately as the roving leaves said region and then increasing more and more rapidly to the initial rate at the drafting nip, the rate of twist in the back zone also falling abruptly at said feeding point, but to a substantially lesser degree, and gradually increasing to the initial rate upon entering said region, the urging point being so near to the nip that the lowest rate of twist in the front zone is sufficient for coherence under the tension arising from the drafting action, and the nearness of the urging point to the nip also resulting in there being a substantial number of fibres gripped at the nip extending backwards from the front zone through the urging point, and deliberately applying pressure to the roving at the urging point to provide within the roving a resistance to the drafting action whereby those backwardly extending fibres are tensioned in the front zone and enabled to communicate their tension to fibres extending forwardly from the back zone through the urging point because of the constantly maintained twist conditions, the result being that the backwardly extending fibres pulled very rapidly through the urging point by the high drafting action bring forward in regular manner fibres from the back zone that have been freed at the feeding point.

2. A process as in claim 1, comprising preventing sensible rotation about its own axis of a length of a roving in the back zone by applying frictional peripheral resistance to that length.

3. A process of single stage drafting textile fibres of the kind in which a roving is forwardly urged at an intermediate point of its length extending between a feeding point and a drafting nip, said process comprising applying a single stage draft of at least 20 to a roving having a predetermined initial twist rate, peripherally confining the roving to a compact cross-sectional form at the urging point, thus avoiding substantial flattening to ribbon form and causing twist to pass continuously through the urging point with the roving from the back zone into the front zone, into which zones the roving has been divided by the urging point, thus maintaining substantial constancy of twist conditions in both zones, sensible rotation of the roving about its own axis being prevented at a region which at least includes the urging point, the rate of twist in the front zone falling abruptly to its lowest degree in the drafting operation immediately as the roving leaves said region and then increasing more and more rapidly to the initial rate at the drafting nip, the rate of twist in the back zone also falling abruptly at said feeding point, but to a substantially lesser degree, and gradually increasing to the initial rate upon entering said region, the urging point being so near to the nip that the lowest rate of twist in the front zone is sufficient for coherence under the tension arising from the drafting action, and the nearness of the urging point to the nip also resulting in there being a substantial number of fibres gripped at the nip extending backwards from the front zone through the urging point, and deliberately loading the confined compact section at the urging point so as to cause peripheral pressure to be applied to the compact sec-

tion and thus provide throughout the compact section a resistance to the drafting action whereby those backwardly extending fibres are tensioned in the front zone and enabled to communicate their tension to fibres extending forwardly from the back zone through the urging point because of the constantly maintained twist conditions, the result being that the backwardly extending fibres pulled very rapidly through the urging point by the high drafting action bring forward in regular manner fibres from the back zone that have been freed at the feeding point.

4. A process of single stage drafting textile fibres of the kind in which a roving is forwardly urged at an intermediate point of its length extending between a feeding point and a drafting nip, said process comprising applying a single stage draft of at least 20 to a roving having a predetermined initial twist rate, applying the high drafting action by a nip offering soft resilience to one side of the roving under pressure adjusted to maintain steady the distance between the urging point and the first nipping of the roving, causing twist to pass continuously through the urging point with the roving from the back zone into the front zone, into which zones the roving has been divided by the urging point, thus maintaining substantial constancy of twist conditions in both zones, sensible rotation of the roving about its own axis being prevented at a region which at least includes the urging point, the rate of twist in the front zone falling abruptly to its lowest degree in the drafting operation immediately as the roving leaves said region and then increasing more and more rapidly to the initial rate at the drafting nip, the rate of twist in the back zone also falling abruptly at said feeding point, but to a substantially lesser degree, and gradually increasing to the initial rate upon entering said region, the urging point being so near to the nip that the lowest rate of twist in the front zone is sufficient for coherence under the tension arising from the drafting action, and the nearness of the urging point to the nip also resulting in there being a substantial number of fibres gripped at the nip extending backwards from the front zone through the urging point, and deliberately applying pressure to the roving at the urging point to provide within the roving a resistance to the drafting action whereby those backwardly extending fibres are tensioned in the front zone and enabled to communicate their tension to fibres extending forwardly from the back zone through the urging point because of the constantly maintained twist conditions, the result being that the backwardly extending fibres pulled very rapidly through the urging point by the high drafting action bring forward in regular manner fibres from the back zone that have been freed at the feeding point.

5. A process as in claim 4, wherein the pressure at the drafting nip is adjusted to provide an angle of incidence to the nip greater than the angle of taper to which the roving has been brought by the high draft.

6. A process as in claim 4, wherein the twist is caused to pass continuously through the urging point by confining the roving to a compact cross-sectional form at that point.

7. A process of single stage drafting textile fibres of the kind in which a roving is forwardly urged at an intermediate point of its length extending between a feeding point and a drafting nip, said process comprising applying a single stage draft of at least 20 to a roving having a

predetermined initial twist rate, causing twist to pass continuously through the urging point with the roving from the back zone into the front zone, into which zones the roving has been divided by the urging point, thus maintaining substantial constancy of twist conditions in both zones, sensible rotation of the roving about its own axis being prevented at a region which at least includes the urging point, the rate of twist in the front zone falling abruptly to its lowest degree in the drafting operation immediately as the roving leaves said region and then increasing more and more rapidly to the initial rate at the drafting nip, the rate of twist in the back zone also falling abruptly at said feeding point, but to a substantially lesser degree, and gradually increasing to the initial rate upon entering said region, preventing any sensible rotation about its own axis of a length of the roving in the front zone by applying frictional peripheral resistance to that length to maintain over that length substantially the initial rate of twist, the length extending to a point so near to the nip that the lowest rate of twist in the front zone is sufficient for coherence under the tension arising from the drafting action, and the urging point also being so near to the nip that a substantial number of fibres gripped at the nip extend backwards from the front zone through the urging point, and

to that length to maintain over that length substantially the initial rate of twist, the length extending to a point so near to the nip that the lowest rate of twist in the front zone is sufficient for coherence under the tension arising from the drafting action, and the urging point also being so near to the nip that a substantial number of fibres gripped at the nip extend backwards from the front zone through the urging point, and 5 deliberately loading the confined compact section at the urging point so as to cause peripheral pressure to be applied to the compact section and thus provide throughout the compact section a resistance to the drafting action whereby those 10 backwardly extending fibres are tensioned in the front zone and enabled to communicate their tension to fibres extending forwardly from the back zone through the urging point because of the constantly maintained twist conditions, the 15 20 result being that the backwardly extending fibres pulled very rapidly through the urging point by the high drafting action bring forward in regular manner fibres from the back zone that have been freed at the feeding point.

25 10. Process as in claim 9, wherein the prevention of sensible rotation in the front zone is effected in a length of the roving immediately emerging from the urging point.

11. A process of single stage drafting textile 30 fibres of the kind in which a roving is forwardly urged at an intermediate point of its length extending between a feeding point and a drafting nip, said process comprising applying a single stage draft of at least 20 to a roving having a 35 predetermined initial twist rate, applying the high drafting action by a nip offering soft resilience to one side of the roving under pressure adjusted to maintain steady the distance between the urging point and the first nipping of the roving, 40 causing twist to pass continuously through the urging point with the roving from the back zone into the front zone, into which zones the roving has been divided by the urging point, thus maintaining substantial constancy of twist conditions in both zones, sensible rotation of the roving about its own axis being prevented at a region which at least includes the urging point, the rate of twist in the front zone falling abruptly to its lowest degree in the drafting operation immediately as the roving leaves said region and then increasing more and more rapidly to the initial rate at the drafting nip, the rate of twist in the back zone also falling abruptly at said feeding point, but to a substantially lesser degree, and gradually increasing to the initial rate upon entering said region, preventing any sensible rotation about its own axis of a length of the roving in the front zone by applying frictional peripheral resistance to that length to maintain over that length substantially the initial rate of twist, the length extending to a point so near to the nip that the lowest rate of twist in the front zone is sufficient for coherence under the tension arising from the drafting action, and the urging point also being so near to the nip that a substantial number of fibres gripped at the nip extend backwards from the front zone through the urging point, and deliberately applying pressure to the roving at the urging point to provide within the roving a resistance to the drafting action whereby those backwardly extending fibres are tensioned in the front zone and enabled to communicate their tension to fibres extending forwardly from the back zone through the urging point because of the constantly maintained twist 55 60 65 70 75

conditions, the result being that the backwardly extending fibres pulled very rapidly through the urging point by the high drafting action bring forward in regular manner fibres from the back zone that have been freed at the feeding point.

12. A process as in claim 11, wherein the pressure at the drafting nip is adjusted to provide an angle of incidence to the nip greater than the angle of taper to which the roving has been brought by the high draft.

13. A process as in claim 11, wherein the twist is caused to pass continuously through the urging point by peripherally confining the roving to a compact cross-sectional form at that point, the pressure applied at the urging point operating throughout this confined compact section to provide the resistance to the drafting action.

14. A process as in claim 11, wherein the prevention of sensible rotation in the front zone is in a length of the roving immediately emerging from the urging point.

15. In apparatus for single stage drafting of a twisted roving of textile fibres, such apparatus being of the type having forward urging means for the roving disposed to divide the distance between a feeding device and a pair of contacting drafting rolls into a back zone and a substantially shorter front zone, the combination comprising: gearing for driving the feeding device and drafting rolls at relative surface speeds to produce therebetween a single stage draft of at least 20; urging means in the form of a pair of members with forwardly movable surfaces, means for supporting said surfaces in operative positions disposed so near the nip of the drafting rolls that the discharge end of the two surfaces is located forwardly of a line tangent to the rear sides of the drafting rolls; external loading means applied to one of the members of the said urging means to apply pressure to the roving in its passage between said means; lateral surfaces disposed in association with the forwardly movable urging surfaces to provide a passage for confining the roving to a compact cross-sectional form; and gearing for driving said urging surfaces forwardly at a speed slightly greater than the surface speed of the feeding device.

16. In apparatus as in claim 15, a channel-shaped member extending over a substantial length of the back zone and constituting a passageway of restricted width for the roving.

17. In apparatus as in claim 16, means for supporting the channel-shaped member immediately adjacent the urging means.

18. In apparatus for single stage drafting of a twisted roving of textile fibres, such apparatus being of the type having forward urging means for the roving disposed to divide the distance between a feeding device and a pair of contacting drafting rolls into a back zone and a substantially shorter front zone, the combination comprising: gearing for driving the feeding device and drafting rolls at relative surface speeds to produce therebetween a single stage draft of at least 20; urging means in the form of a pair of members with forwardly movable surfaces shaped to provide a passage therebetween for confining the twisted roving in passing therethrough to a compact cross-sectional form, means for supporting said surfaces in operative positions disposed so near the nip of the drafting rolls that at least portions of said surfaces are located forwardly of a line tangent to the rear sides of the two drafting rolls; external loading means applied to one of the members of said urging means

to apply peripheral pressure to the compacted roving in said passage; and gearing for driving said surfaces forwardly at a speed slightly greater than the surface speed of the feeding device.

19. In apparatus as in claim 18, the members of the urging means being in the form of a pair of rollers, one with flanges constituting lateral confining surfaces movable with the rollers, and the other roller fitting between the flanges.

20. In apparatus for single stage drafting of a twisted roving of textile fibres, such apparatus being of the type having forward urging means for the roving disposed to divide the distance between a feeding device and a pair of contact-

ing drafting rolls into a back zone and a substantially shorter front zone, the combination comprising: one drafting roll with a resilient surface of low hardness and a co-operating hard fluted roll; gearing for driving the feeding device and drafting rolls at relative surface speeds to produce therebetween a single stage draft of at least 20; urging means in the form of a pair of members with forwardly movable surfaces, means for supporting said surfaces in operative posi-

tions disposed so near the nip of the drafting rolls that the discharge end of the two surfaces is located forwardly of a line tangent to the rear sides of the drafting rolls; external loading means applied to one of the members of the said urging means to apply pressure to the roving in its passage between said means; lateral surfaces disposed in association with the forwardly movable urging surfaces to provide a passage for confin-

ing the roving to a compact cross-sectional form; and gearing for driving said urging surfaces forwardly at a speed slightly greater than the surface speed of the feeding device.

21. In apparatus as in claim 20, loading means for the drafting device sufficient to produce by compression of the resilient roll an angle of incidence to the drafting nip greater than 10°.

22. In apparatus for single stage drafting of a twisted roving of textile fibres, such apparatus being of the type having forward urging means for the roving disposed to divide the distance between a feeding device and a pair of contacting drafting rolls at relative surface speeds to produce therebetween a single stage draft of at least 20; urging means in the form of a pair of members with forwardly movable surfaces shaped to pro-

vide a passage therebetween for confining the twisted roving in passing therethrough to a compact cross-sectional form, means for supporting said surfaces in operative positions disposed so near the nip of the drafting rolls that at least portions of said surfaces are located forwardly of a line tangent to the rear sides of the two drafting rolls; external loading means applied to one of the members of said urging means to apply

peripheral pressure to the compacted roving in said passage; and gearing for driving said surfaces forwardly at a speed slightly greater than the surface speed of the feeding device.

23. In apparatus for single stage drafting of a twisted roving of textile fibres, such apparatus being of the type having forward urging means for the roving disposed to divide the distance between a feeding device and a pair of contacting drafting rolls into a back zone and a sub-

stantially shorter front zone, the combination

comprising: gearing for driving the feeding device and drafting rolls at relative surface speeds to produce therebetween a single stage draft of at least 20; urging means in the form of a pair of rollers, one with flanges constituting lateral confining surfaces movable with the rollers, and the other roller fitting between the flanges; means for supporting said urging rollers in operative positions disposed so near to the nip of the drafting rolls that at least part of the rollers is located forwardly of a line tangent to the rear sides of the drafting rolls; external loading means applied to one of the urging rollers to apply pressure to the roving in its passage through said rollers; and gearing for driving said urging rollers forwardly at a speed slightly greater than the surface speed of the feeding device.

24. In apparatus as in claim 21, loading means for the drafting device sufficient to produce by compression of the resilient roll an angle of incidence to the drafting nip greater than 10°.

25. In apparatus for single stage drafting of a twisted roving of textile fibres such apparatus being of the type having forward urging means for the roving disposed to divide the distance between a feeding device and a pair of contacting drafting rolls into a back zone and a substantially shorter front zone, the combination comprising: gearing for driving the feeding device and drafting rolls at relative surface speeds to produce therebetween a single stage draft of at least 20; urging means in the form of a pair of members with forwardly movable surfaces, means for supporting said surfaces in operative positions disposed so near the nip of the drafting rolls that the discharge end of the two surfaces is located forwardly of a line tangent to the rear sides of the drafting rolls; external loading means applied to one of the members of the said urging means to apply pressure to the roving in its passage between said means; lateral surfaces disposed in association with the forwardly movable urging surfaces to provide a passage for confining the roving to a compact cross-sectional form; a channel-shaped member extending forwardly of the urging means over a substantial length of the front zone and constituting a passageway of restricted width for the roving; and gearing for driving said urging surfaces forwardly at a speed slightly greater than the surface speed of the feeding device.

26. In apparatus as in claim 25, the channel-shaped member being disposed immediately adjacent the urging means.

27. In apparatus as in claim 25, the channel-member having a passageway of rectangular cross-section.

28. In apparatus for single stage drafting of a twisted roving of textile fibres, such apparatus being of the type having forward urging means for the roving disposed to divide the distance between a feeding device and a pair of contacting drafting rolls into a back zone and a substantially shorter front zone, the combination comprising: gearing for driving the feeding device and drafting rolls at relative surface speeds to produce therebetween a single stage draft of at least 20; urging means in the form of a pair of members with forwardly movable surfaces shaped to provide a passage therebetween for confining the twisted roving in passing therethrough to a compact cross-sectional form, means for supporting said surfaces in operative positions disposed so near the nip of the draft-

ing rolls that at least portions of said surfaces are located forwardly of a line tangent to the rear sides of the two drafting rolls; external loading means applied to one of the members of said urging means to apply peripheral pressure to the compacted roving in said passage; a channel-shaped member extending forwardly of the urging means over a substantial length of the front zone and constituting a passageway of restricted width for the roving; and gearing for driving said surfaces forwardly at a speed slightly greater than the surface speed of the feeding device.

29. In apparatus for single stage drafting of a twisted roving of textile fibers, such apparatus being of the type having forward urging means for the roving disposed to divide the distance between a feeding device and a pair of contacting drafting rolls into a back zone and a substantially shorter front zone, the combination comprising: gearing for driving the feeding device and drafting rolls at relative surface speeds to produce therebetween a single stage draft of at least 20; urging means in the form of a pair of rollers, one with flanges constituting lateral confining surfaces movable with the rollers, and the other roller fitting between the flanges; means for supporting said urging rollers in operative positions disposed so near to the nip of the drafting rolls that at least part of the rollers is located forwardly of a line tangent to the rear sides of the drafting rolls; external loading means applied to one of the urging rollers to apply pressure to the roving in its passage through said rollers; a channel-shaped member extending forwardly of the urging rollers over a substantial length of the front zone and constituting a passageway of restricted width for the roving; and gearing for driving said urging rollers forwardly at a speed slightly greater than the surface speed of the feeding device.

30. In apparatus as in claim 29, the channel-shaped member being disposed immediately adjacent the urging rollers.

31. In apparatus for single stage drafting of a twisted roving of textile fibres, such apparatus being of the type having forward urging means for the roving disposed to divide the distance between a feeding device and a pair of contacting drafting rolls into a back zone and a substantially shorter front zone, the combination comprising: one drafting roll with a resilient surface of low hardness and a co-operating hard fluted roll; gearing for driving the feeding device and drafting rolls at relative surface speeds to produce therebetween a single stage draft of at least 20; urging means in the form of a pair of members with forwardly movable surfaces, means for supporting said surfaces in operative positions disposed so near the nip of the drafting rolls that the discharge end of the two surfaces is located forwardly of a line tangent to the rear sides of the drafting rolls; external loading means applied to one of the members of the said urging means to apply pressure to the roving in its passage between said means; lateral surfaces disposed in association with the forwardly movable urging surfaces to provide a passage for confining the roving to a compact cross-sectional form; a channel-shaped member extending forwardly of the urging means over a substantial length of the front zone and constituting a passageway of restricted width for the roving; and gearing for driving said urging surfaces forwardly at a speed slightly greater than the surface speed of the feeding device.

slightly greater than the surface speed of the feeding device.

32. In apparatus as in claim 31, loading means for the drafting device sufficient to produce by compression of the resilient roll an angle of incidence to the drafting nip greater than 10°.

33. In apparatus for single stage drafting of a twisted roving of textile fibres, such apparatus being of the type having forward urging means for the roving disposed to divide the distance between a feeding device and a pair of contacting drafting rolls into a back zone and a substantially shorter front zone, the combination comprising: gearing for driving the feeding device and drafting rolls at relative surface speeds to produce therebetween a single stage draft of at least 20; urging means in the form of a pair of rollers, one with flanges constituting lateral confining surfaces movable with the rollers, and the other roller fitting between the flanges; means for supporting said urging rollers in operative positions disposed so near to the nip of the drafting rolls that at least part of the rollers is located forwardly of a line tangent to the rear sides of the drafting rolls; external loading means applied to one of the urging rollers to apply pressure to the roving in its passage through said rollers; a channel-shaped member extending forwardly of the urging rollers over a substantial length of the front zone and constituting a passageway of restricted width for the roving; and gearing for driving said urging surfaces forwardly at a speed slightly greater than the surface speed of the feeding device.

34. In apparatus as in claim 33, the channel-shaped member being disposed immediately adjacent the urging means.

35. In apparatus as in claim 33, the channel-shaped member having a passageway of rectangular cross-section.

36. In apparatus as in claim 33, loading means for the drafting device sufficient to produce by compression of the resilient roll an angle of incidence to the drafting nip greater than 10°.

37. In apparatus for single stage drafting of a twisted roving of textile fibres, such apparatus being of the type having forward urging means for the roving disposed to divide the distance between a feeding device and a pair of contacting drafting rolls into a back zone and a substantially shorter front zone, the combination comprising: gearing for driving the feeding device and drafting rolls at relative surface speeds to produce therebetween a single stage draft of at least 20; urging means in the form of a pair of rollers, one with flanges constituting lateral confining surfaces movable with the rollers, and the

other roller fitting between the flanges, said urging rollers being of diameters not greater than one-tenth of the diameters of said drafting rollers; mounting means for said urging rollers permitting same to be operatively positioned just out of contact with the drafting rollers; external loading means applied to one of the urging rollers to apply pressure to the roving in its passage through said rollers; and gearing for driving said urging rollers forwardly at a speed slightly greater than the surface speed of the feeding device.

38. In apparatus for single stage drafting of a twisted roving of textile fibres, such apparatus being of the type having forward urging means for the roving disposed to divide the distance between a feeding device and a pair of contacting drafting rolls into a back zone and a substantially shorter front zone, the combination comprising: gearing for driving the feeding device and drafting rolls at relative surface speeds to produce therebetween a single stage draft of at least 20; urging means in the form of a pair of rollers, one with flanges constituting lateral confining surfaces movable with the rollers, and the other roller fitting between the flanges, said urging rollers being of diameters not greater than one-tenth of the diameters of said drafting rollers; mounting means for said urging rollers permitting same to be operatively positioned just out of contact with the drafting rollers; external loading means applied to one of the urging rollers to apply pressure to the roving in its passage through said rollers; a channel-shaped member extending forwardly of the urging rollers over a substantial length of the front zone and constituting a passageway of restricted width for the roving; and gearing for driving said urging rollers forwardly at a speed slightly greater than the surface speed of the feeding device.

GEOFFREY HILL AMBLER.
